3,311,300

CALCULATING MACHINES

Francis J. Caldwell, West Carrollton, Richard D. Joyce, Dayton, and Clarence L. Coleman, Tipp City, Ohio, assignors to The National Cash Register Company, Dayton, Ohio, a corporation of Maryland

Filed July 22, 1964, Ser. No. 384,367
16 Claims. (Cl. 235—201)

This invention relates to an automatic calculating machine and more particularly to a calculator constructed of a plurality of fluid pressure relays and capable of performing addition, subtraction, multiplication, and division operations.

It is among the objects of this invention to provide an improved calculating machine which is of a low-cost construction and operates with increased efficiency while performing the various computing operations.

Another object of the invention is to provide an improved calculating machine having a hydraulically-operated ten-key keyboard which precludes the operation of more than one key at a time.

Another object of this invention is to provide an improved calculating machine having a hydraulically-operated ten-key keyboard which prevents insignificant zero key operations.

A further object of this invention is to provide a hydraulically-operated calculating machine having a full parallel binary-coded decimal adder with means for transferring a carry signal to each appropriate stage of the adder at a relatively high rate of speed.

Another object of this invention is to provide a hydraulically-operated calculating machine having fluid pressure relays constructed for improved operation.

Still another object of this invention is to provide an improved hydraulically-operated calculating machine having fluid pressure relays capable of retaining their state of operation in case of a power failure.

Other objects and advantages will be apparent from a consideration of the following description in conjunction with the appended drawings, in which:

FIG. 1 is a perspective view of the improved hydraulic calculator;

FIG. 2 is a right side sectional view of the calculator, showing the arrangement of the various logic packages and the fluid pressure drive system;

FIG. 3 is a detailed view of one type of a single-acting fluid pressure relay used in the calculator;

FIG. 4 is a schematic representation of the relay of FIG. 3 in electrical form;

FIG. 5 is a detailed view of a double-acting fluid pressure relay used in the calculator;

FIG. 6 is a detailed view of a double-stacked relay of the type disclosed in FIG. 5;

FIG. 7 is a detailed view of a double-stacked relay of the type disclosed in FIG. 3;

FIG. 8 is a detailed view of a triple-stacked relay of the type disclosed in FIG. 3;

FIG. 9 is a detailed view of a four-stacked relay of the type disclosed in FIG. 3;

FIG. 10 is a detailed view of a modified relay of the type disclosed in FIG. 3 used in the calculator to amplify the fluid pressure;

FIG. 11 is a detailed view of another modified relay of the type disclosed in FIG. 3 used in the calculator to amplify the fluid pressure;

FIG. 12 is a schematic representation of the relay disclosed in FIG. 3;

FIG. 13 is a schematic representation of the relay disclosed in FIG. 5;

FIG. 14 is a schematic representation of the fluid am-

2

plifier used in each indicator bank utilized in the relays of FIGS. 11 and 12;

FIG. 15 is a plan view of the ten-key keyboard used in the calculator;

FIG. 16 is a sectional view of the keyboard logic package taken along the line 16—16 of FIG. 15;

FIG. 17 is a detailed sectional view of the keyboard taken on the line 17—17 of FIG. 15, showing the key plate assembly of the fluid control key bank;

FIG. 18 is a detailed view of the key plate of FIG. 17 with the control keys removed;

FIG. 19 is a detailed sectional view of the keyboard taken on the line 19—19 of FIG. 15, showing the key plate assembly of the second control key bank;

FIG. 20 is a detailed view of the key plate of FIG. 19 with the control keys removed;

FIG. 21 is a detailed sectional view of the keyboard taken on the line 21—21 of FIG. 15, showing the key plate assembly of an amount bank;

FIG. 22 is a detailed view of the key plate of FIG. 21 with the amount keys removed;

FIG. 23 is a detailed sectional view of the keyboard taken on the line 23—23 of FIG. 15, showing the key plate assembly of the third control key bank;

FIG. 24 is a detailed view of the key plate of FIG. 21 with the control keys removed;

FIG. 25 is a detailed view of a typical indicator digit assembly;

FIG. 26 is a side sectional view of a relay plate of the digit assembly, showing the booster pistons;

FIG. 27 is a detailed view of a port plate which is included in the digit assembly;

FIG. 28 is a detailed view of a channel plate which is part of the digit assembly;

FIG. 29 is a side sectional view of the binary conversion unit used to control the printer;

FIG. 30 is a detailed side view of the slotted yoke members for controlling the movement of sensing pins;

FIG. 31 is an end view of the slotted yoke members;

FIG. 32 is a detailed view of the five code slides used in the binary conversion unit, showing the relative positions of the slots contained in each of the slides;

FIG. 33 is a detailed view of the cam-driven actuating mechanism for the slotted yoke members;

FIG. 34 is a detailed view of the sensing assembly mounted on the differential member of the printer mechanism;

FIG. 35 is a block diagram of the logic packages used in the calculator;

FIG. 36 is a schematic diagram of the control key portion of the keyboard, showing the various relays controlled by the keys;

FIG. 37 is a schematic diagram of the amount key portion of the keyboard, showing the relay controlled by the keys;

FIG. 38 is a block diagram of the logic circuits which compose the control circuit section set out in FIG. 35;

FIG. 39 is a logical diagram of the timing clock circuit and associated circuitry;

FIGS. 40A, 40B, and 40C, taken together, constitute a logical diagram of the "K" register shift counter and associated circuitry;

FIGS. 41A and 41B, taken together, constitute a logical diagram of the sequence counter and associated circuitry;

FIGS. 42A and 42B, taken together, constitute a logical diagram of the various circuits of the control keyboard register;

FIG. 43 is a logical diagram of the control circuit for initiating a printer operation;

FIG. 44 is a logical diagram of the other circuits of the control keyboard register;

FIGS. 45A and 45B, taken together, constitute a logical diagram of the Symbol Row Printer circuits;

FIGS. 46A, 46B, and 46C, taken together, constitute a logical diagram of various control circuits used in the calculator;

FIGS. 47A, 47B, and 47C, taken together, constitute a logical diagram of a shift counter used in multiplication and division operations;

FIG. 48 is a logical diagram of the circuits composing the selector unit;

FIGS. 49A and 49B, taken together, constitute a logical diagram of the binary adder and associated circuitry;

FIG. 50 is a logical diagram of the "M" or Memory register;

FIG. 51 is a logical diagram of the "K" or Keyboard register;

FIG. 52 is a logical diagram of the "A" or Accumulator register;

FIG. 53 is a flow diagram of the sequence of operations executed in carrying out a multiplication operation of the calculator;

FIG. 54 is a flow diagram of the sequence of operations executed in carrying out a division operation;

FIG. 55 is a detailed view of a pair of modified relays constituting a flip-flop which retains its position if a fluid pressure failure occurs; and

FIG. 56 is a detailed end view of the relays of FIG. 55.

Referring to FIG. 1, there is shown an overall view of the hydraulic calculator, which includes a ten-key keyboard 21, a keyboard indicator 22, a memory indicator 23, an accumulating indicator 24, and a control knob 26 for positioning the tape 25. A housing 27 encloses the printing mechanism and the various logic packages, which will now be described.

As shown in FIG. 2, there is located within the front portion of the housing 27 a leak-proof compartment 28, formed of a frame member 29. Located within the compartment are the various logic packages, which are actuated by hydraulic fluid in a manner to be described hereinafter. Included in these packages are the keyboard 30, the indicator package 31, which is of the same construction for all three indicators, the "K" or Keyboard register 32, the "M" or Memory register 33, the Adder and Selector 34, and the "A" or Accumulating register and Control unit package 35. Secured to the rear frame member 29 by means of screws 36 is the printer logic package 37, which is connected through the frame member 29 to a binary conversion unit 38, located in the rear of the housing 27. Associated with the conversion unit is a printing mechanism, a portion of which is indicated as 39. This particular printing mechanism is the same as that disclosed in United States Patent No. 2,905,382, issued to Guido Carnacina on Sept. 22, 1959.

Also located in the rear portion of the housing is the hydraulic fluid supply system. This system consists of a positive displacement pump 40, mounted to the bottom frame member 41 of the housing. The rear portion of the housing also includes a piping system, which consists of the pipe 42, the single pipe T 43, the mid-pressure regulator 44, and the double pipe T 45, which is connected to the output port 46 of the pump. The other end of the pipe 42 is connected to an aperture located in the frame member 29 together with a seal 47. A mid-pressure of five pounds of fluid pressure is supplied to the logic packages over this system. A second pipe 48 is connected to the double pipe T 45, while its other end is connected to the frame member 29 in the same manner as the pipe 42. Mounted in this pipe is a high-pressure relay valve 49, which does not open until the pressure of the fluid coming from the pump exceeds the mid-pressure. The pressure eventually reaches fifteen pounds per square inch. This fifteen pounds of fluid pressure constitutes the high-pressure fluid used in the logic system. A return pipe 50, secured to the lower portion of the frame member 29, is connected through a filter 51 and

a pipe T 52 to the inlet port 53 of the pump. Within the compartment 28, a fluid sump is maintained to a height shown by the dotted line 54. The pressure on the sump is atmospheric, which constitutes the low, or native, pressure used in the logic packages. A mid-pressure relief valve 55 and a pipe T 56 are located between the pipe Ts 43 and 52 to provide an overflow path for the mid-pressure fluid system. A pipe 57, connected between the pipe Ts 56 and 45, and a pressure relief valve 58 provide a similar overflow path for the high-pressure system.

Inside the compartment 28, a pair of tubes 59, 60 transmits the mid and high fluid pressures from the pipe 42, 48 to each of the logic packages. As shown in FIG. 2, the tubes are connected to a series of feed blocks 61, each of which contains a plurality of channels (not shown) for transmitting the required fluid pressures to its associated logic packages in the manner required.

Referring now to FIG. 3, there is shown the basic hydraulic logic element used in the logic packages. This element is similar to the element disclosed in United States Patent No. 3,057,551, issued to Thomas L. Etter on Oct. 9, 1962, in that the element is a flat piston 62, located in a cavity 63, which in turn is contained in a thin sheet of material. The material may be of any type of metal or plastic. The piston 62 used in the present disclosure is stamped out of steel. Each cavity 63 has two inlet ports 64, 65 and an outlet port 66, which are located in adjacent sheets and which are perpendicular to the piston 62. The ports are connected by channels, most of which are perpendicular to the piston 62 but for purposes of illustration are indicated in a horizontal plane by dotted lines. Each piston contains a pair of apertures 67 at either of its ends and an elongated slot 68 located at its mid section. This positioning of the apertures 67, the slots 68, and the ports 64, 65, and 66 so that the fluid flow is perpendicular to the face of the flat piston 62 reduces the fluid leakage around the piston that is normally present with the edge-type construction disclosed in the aforementioned Etter United States patent. The positioning of the apertures and the slots in the face of the piston rather than on its edge allows for the machining of the adjacent faces of the piston and the plates in which the connecting channels are located. This allows for closer tolerances between the adjacent surfaces, thus improving efficiency of operation. The piston 62 is actuated by providing a high-pressure signal at one end of the cavity in a channel 69 and a mid-pressure signal at the other end in a channel 70. When these two pressures are applied, the piston moves to a lower position, thereby connecting the lower inlet port 65 to the outlet port 66 by means of the slot 68. Relieving the high pressure in the channel 69 to atmosphere allows the piston 62 to return to the position shown in FIG. 3, whereby the upper inlet port 64 is connected to the outlet port 66. If high and low pressures are introduced to each of the input ports 64 and 65, respectively, it can be seen that, by switching the control pressures in the channel 69, either one of the inlet pressures can be selected to be fed through the outlet port 66. This operation is similar to the operation of an electric relay as represented in FIG. 4. The inputs and the outputs are represented by the switching contacts 64a, 65a; the pump 40 by the battery; high- or low-pressure signals to the channel 69 by the closing and opening of the circuit to the solenoid 71; and mid-pressure signals by the return of the center contact. Thus the logic elements may be characterized as fluid pressure relays.

Another type of relay used in the logic circuits of the calculator is shown in FIG. 5. The construction of this piston 72 is similar to that of the piston 62 except that it has two elongated slots 73, 74. The cavity 75 has three input ports, 76, 77, and 78, and two output ports, 79 and 80. The operation of this double-acting relay is the same as that for the single-acting relay 62. When the

piston is in its upper position, as shown in FIG. 5, the inlet port 76 is connected to the outlet port 79, while the inlet port 77 is connected to the outlet port 80. When the piston is moved to its lower position upon the application of a high pressure, the inlet port 77 is connected to the outlet port 79, while the lower inlet port 78 is connected to the outlet port 80. This element is also disclosed in the previously-cited Etter United States patent. FIGS. 6 through 11 show modifications of these two basic relays which are used in the logic circuits herein-after described. FIG. 6 shows a double-stacked piston of the type disclosed in FIG. 5. FIG. 7 shows a double-stacked piston of the single-acting relay 62, while FIGS. 8 and 9 show a triple-stacked piston and a four-stacked piston of the same relay, respectively. FIGS. 10 and 11 show two variations of the single-acting relay 62. The construction of both of these latter relays provides a booster action to the pressure signal, so that the signal may actuate mechanical elements. The use of these relays is limited to the indicator and printer assemblies.

FIG. 12 shows the single-acting relay 62 and FIG. 13 the double-acting relay 72 in the diagrammatic form used in the logic circuits. As described above, when the control channels 69 of both relays have a high, or positive, pressure, signals applied thereto, the inlet port 65 of the relay 62 is connected to the outlet port 66, while the inlet ports 77, 78 of the relay 72 are connected to the outlet ports 79, 80, respectively. When a low or negative pressure signal is applied to the control channel 69, the inlet port 64 of the relay 62 is applied to the outlet port 66, while the inlet ports 76, 77 of the relay 72 are applied to the outlet ports 79, 80. As will be described more fully in the description of the logic circuits, relays of the type shown in FIGS. 12 and 13 are used to construct flip-flop circuits, shift registers, binary adders, and other circuits.

Referring now to FIG. 15, there is shown a plan view of the keyboard used with the calculator. Positioned on the left-hand portion of the keyboard are four non-motorized keys: the "Mode" key 84, which disables the printing of either the "K" or "M" registers; the "%" key 81, used with the Multiply key 89 to print the product with the decimal shifted two places to the left; the "M" key 82, used with control keys for controlling the operation of the "M" register; and the "Clear" key 83, which is used to reset the calculator to its home position. All of the remaining control keys are motorized, so that they operate the calculator when they are depressed. Included in these are the "Enter Dividend" key 85, which controls the "K" and "A" registers during a division operation; the "Divide" key 86, which controls the "A," "K," and "M" registers during a division operation; the "Enter Multiplier" key 87, which controls the "K" and "M" registers during a multiplication operation; the "Negative Multiplier" key 88 and the "Multiply" key 89, which control the "A," "K," and "M" registers during a multiplication operation; the "Total" key 90 and the "Sub-Total" key 91, which control the operation of the "A" register; the "Add" key 92 and the "Subtract" key 93, which control the "A" and "K" registers; and the "Non-Add" key 94, for controlling the "K" register. The function of each of these keys and their controls of the various logic packages will be explained more fully hereinafter with respect to the explanation of the logic drawings.

The construction of the keyboard package 30 (FIG. 2) is shown more clearly in FIG. 16, which is a section taken through the control keys 85 to 89 inclusive. As shown, the package is composed of a number of plates of different thicknesses, which are held together by a plurality of screws (not shown) extending from left to right. Included in the package are a number of keyboard piston plates 95, in which are located the logic relays of the type disclosed in FIGS. 12 and 13, and a number of associated keyboard port plates 96, located on either side

of each piston plate. Each port plate contains only ports or cavities. An example of a port plate is shown in FIG. 27, while FIG. 26 shows an example of a piston plate. Both of these plates are used in the indicator package. FIG. 28 shows a channel plate which also is used in the indicator package and which contains channels and holes.

The keyboard package also includes a number of keyboard key plates 97, in which are located the various amount and control keys. FIGS. 17 to 24 inclusive are detailed views of the various key plates used in the keyboard package. FIG. 21 is a detailed view of a typical key plate assembly, showing a number of amount keys 62a and the control key 88 mounted in a key plate 97. Each of the amount and control keys comprises a key stem 98 (FIG. 21) and a key tip 99, mounted to the key stem by a nut 100. A pair of washers 101 are mounted on the key stem by the nut 100. Positioned between the washers of each of the keys of the keyboard is a rubber mat 102, which acts to seal the hydraulic fluid within the keyboard package.

Each of the key stems 98 is slidably mounted in a slot 103, located in the key plate 97. Each of the keys is seated in a top cut-out portion 104 of the key plate by means of a spring 105. To keep the key stems located within the slot, the lower portion of the key stems of the keys has a protrusion 106, which engages the upper face of a cut-out portion 107, located at the bottom of each key plate. The protrusions 106 may vary in design, as may be seen from FIGS. 17, 19, 21, and 23.

Associated with the top transverse bank of control keys (FIG. 15) and the two right side banks is an interlock system which comprises a number of steel rolls 108 (FIGS. 15, 16, 19, 20, 21, and 23) positioned in a slot 109, located in the plates of the keyboard package. As shown in FIG. 16, the rolls are located adjacent to the bottom end of each of the key stems of the top row of control keys and are also located in a keyboard port plate 110, positioned between the two right side banks of control keys. Depression of any control key in the top roll moves its key stem into engagement with the rolls 108, forcing the rolls to move to the right, as viewed in FIG. 16. This movement results in the right end roll's engaging one end of a lockout plunger 111 (FIG. 16), located within the keyboard plate, and moving the plunger to the right against the action of a spring 112. This action results in the other end of the plunger 111 being moved into the slot 109 of the port plate 110, thus blocking the movement of the rolls located in the slot. It is seen from this arrangement that, once the control key has been depressed, all of the rolls are prevented from moving until the depressed control key has been released. This system is restored under the action of the spring 112. Each of the control keys in the first right side control bank (FIG. 17) and the second right side control bank (FIG. 19) has mounted on its lower end a key stem stud 113 (FIGS. 17 and 19), which extends through a slot 114, located in the bottom of the plate, and into the slot 109 of the port plate 110 adjacent the rolls 108. Depression of any of these control keys moves its associated key stem stud into engagement with the rolls 108, locking out any other control key. This is accomplished by the positioning of the front rolls 115a (FIG. 15) adjacent to the end of the plunger 111, thus blocking the lateral movement of the plunger.

As will be disclosed hereinafter with relation to the logic drawings of the amount keyboard, there is provided an arrangement whereby the depression of any two amount keys simultaneously results in only the lower order key's being effective. Thus no mechanical interlock for the amount keys is provided.

Referring to FIGS. 17, 19, 21, and 23, each key stem is illustrated as having a number of apertures 115 and slots 116. These apertures and slots coact with a pre-determined number of ports 117, located in the slot 103

(FIGS. 18, 20, 22, and 23) of the key plate. As will be described more fully hereinafter, depression of any of the amount keys results in the establishment of a number of pressure signals representing the decimal digit in binary form. The same results occur when any of the control keys are depressed, but the binary code for each of the keys is arbitrarily assigned. Thus the key stems 98 act in the same manner as the piston 62 (FIG. 3), described previously.

Referring to FIG. 1, it will be seen that the indicators 22 and 23 have a capacity of twelve digits each, while the indicator 24 has a capacity of thirteen digits. Each indicator package 31 (FIG. 2) is composed of a number of digit assemblies, each assembly including an indicator piston plate 118 (FIG. 25), a relay plate 119 (FIG. 26), a port plate 120 (FIG. 27), and a channel plate 121 (FIG. 28). Each digit assembly controls the indication of one digit. In addition, there are two end plates (not shown), which are of solid construction, one having the configuration of the piston plate 118, while the other has the configuration of the channel plate 121. The function and the construction of the plates which compose the indicator assembly are similar to the function and the construction of the keyboard plates described previously. Each plate has a plurality of holes 122 for accommodating screws (not shown) by means of which the plates are assembled. Mounted in the plates 119 are four booster relays 123 of the type disclosed in FIG. 10. Associated with each of these relays is a second booster relay 124, of the type disclosed in FIG. 11. Each combination of relays 123 and 124 (FIG. 26) constitutes a binary bit section of the digit assembly. The function of these two relays is to amplify the pressure signal which is transmitted from the logic packages in a manner that will be described more fully hereinafter. Since the logic packages of the calculator operate on a four-bit binary coded decimal system, each pressure signal sent to the digit assembly represents a binary bit of the decimal digit to be displayed.

To translate the binary coded information into a decimal digit, there are mounted in a slot 125, located in the plate 118 (FIG. 25), a number of pistons 126, 127, 128, 129, and 130, each having one or more interlocking arms 131 of varying lengths. With the end piston 126 being secured to the plate 110 by means of a rivet 132, each of the remaining pistons is slidably mounted in the slot 125 engaging the arms 131 of the adjacent piston. The area formed by the interconnecting adjacent arms 131 constitutes a chamber 126a, into which pressure signals from the booster piston 123 are introduced. It is seen from FIG. 25 that four chambers are so formed, the size of each being determined by the length of the arms 131 of the adjacent pistons. Each chamber represents one of the binary weights, one, two, four, and eight, the size of the chamber varying accordingly. Upon a positive pressure's being introduced into any of the chambers 126a, the piston to the right of the chamber is moved to the right until a stop surface 133 of each adjacent arm is engaged. This movement is transmitted to each succeeding piston on the right, resulting in the positioning of the piston 130 a distance commensurate with the total of the binary weights of the pistons so actuated.

The piston 130 has, on its upper surface, a number of tooth portions 134, forming a rack which drives an indicator segment 135, rotatably mounted on the plate 118 by a stud 136. The segment is normally urged clockwise, as viewed in FIG. 25, by a spring 137, mounted between the segment and the plate. Located on top of the segment are the numerals 0 to 9 inclusive. With this arrangement, if a positive signal, which, as will be described hereinafter, represents a binary "1," with a weight of eight, is fed into the fourth, or last, chamber 126a, the piston 130 moves to the right a predetermined distance, which movement is transmitted to the indicator segment 135 through the rack 134 and the pinion end 138 of the segment. This results in the segment's being rocked coun-

ter-clockwise against the action of the spring 137 to display the digit 8 to the keyboard. As soon as the pressure signals are removed from the chamber 126a, the spring 137 returns the pistons 127, 128, 129, and 130 and the segment 135 to their home positions.

Referring to FIG. 14, there is shown a schematic drawing of the booster relays 123 and 124 of a typical binary coded bit section. During an operation of the calculating machine, a positive signal representing a binary bit of "1" is transmitted over a channel 139 (FIGS. 14, 25, 26, 27, and 28) to the relay 124, thus transferring the piston so as to connect the lower input channel to the output channel. At this time, the pressure signal in the input channel is negative due to a control relay 140 having its piston oriented upwardly, thus supplying a negative pressure to the lower input port of the relay 124. The relay 140 is a control relay which prevents the indicator segment 135 from being set during the machine operation. When the machine operation ends, a positive control pressure signal is applied to the control port of the relay 140 over a channel 143a, resulting in a positive pressure signal's being transmitted over a channel 141 (FIG. 28) to the relay 124, which in turn transmits the pressure signal over a channel 142 (FIG. 28) to the control port of the booster relay 123. The downward orientation of the piston of the relay 123 connects the lower input port of the relay to the output port, thus supplying a positive pressure signal to one of the chambers 126a, formed by the associated pistons 126 to 130 inclusive. Thus each of the required indicator pistons 126 to 130 inclusive is actuated to position the indicator segment 135 for displaying the decimal digit represented by the binary coded signal pressure introduced into the indicator pistons at the end of a machine operation.

Referring now to FIGS. 29 to 34 inclusive, there is a disclosure of details of the printer binary conversion unit indicated as 38 in FIG. 2. The printing mechanism used in the calculator to print out the required information is of the same construction as that disclosed in United States Patent No. 2,905,382, issued to Guido Carnacina, cited previously. The function of the binary conversion unit which will now be described is to convert the binary coded information represented by the fluid pressure signals generated as part of a machine operation into a decimal signal for operating the printing mechanism in the manner disclosed in the above cited Carnacina United States patent. Thus only those parts of the printing unit which are required for purposes of explanation will be indicated. Reference should be made to the above-cited Carnacina United States patent for any further disclosure of the printing mechanism and its operation.

As shown in FIG. 4 and more particularly in FIG. 29, mounted within the compartment 28 and to the rear frame member 29 is the printer coupling housing 37, containing fifteen rows of four pistons each. Thirteen of the rows will each control the printing of the decimal digits 0 to 9 inclusive, while the other two rows will each control the printing of some eight different symbols. The four pistons 143 to 146 inclusive each represent the binary coded weights one, two, four, and eight, respectively. The pistons are slidably mounted in a piston plate 147, which is mounted to the housing 37 by screws 148. Mounted adjacent to the piston plate are a coupling gasket 149 and a coupling plate 150. Both of these members are mounted to the housing 37 by screws 151.

Each of the pistons 143 to 146 inclusive of each row is connected to the logic package of the calculator by means of a support logic package 152, (FIG. 2) and the various storage registers 32, 33, and 35, as will be disclosed in the description of the operation of the logic package. As will be described more fully hereinafter, positive pressure signals, representing the binary bit of "1," will be generated for transmittal to the pistons 143 to 146 inclusive for the printing of a decimal digit.

Secured to the end of each piston is a lever 153, which is rotatably mounted to one end of a bell crank 154. The bell crank 154 in turn is rotatably mounted on a shaft 155, supported between the walls of the housing 37. The other end of the lever 153 has a recessed portion 156, which accommodates one end of a compression spring 157. The other end of the spring 157 engages the cover 158 of a diaphragm assembly consisting of a cover 158, a diaphragm 159 for sealing in the hydraulic fluid, and a shield 160. This assembly is mounted on a gasket 161 to the housing 37 by means of screws 162 through a cut-out portion located in the rear frame member 29.

The diaphragm 159 has a number of apertures, into which is inserted the slotted portion 163 of a sensing pin 164. As shown in FIG. 29, there is one pin 164 for each of the pistons 143 to 146 inclusive. One end of the pin 164 is slidably mounted in the cover 158, while the other end is mounted in a guide plate 165. Engaging the end of the sensing pin 164 within the guide plate is one end of a code bar pin 166, the other end of which extends through and is supported by a pin holder 167. A spring 168, positioned over each pin 166 and mounted between a head portion 169 of the pin 166 and a recessed portion 170 of the pin holder 167, normally urges both the code bar pin 166 and the sensing pin 164 leftwardly as viewed in FIG. 29.

Both the guide plate 165 and the pin holder 167 are mounted to a pair of support plates 171 by means of screws 172. The guide plate 165 in turn is mounted to the cover 158 by means of screws 173 (FIG. 31). Thus the assembly is rigidly supported on the cover 158. To control the movement of the sensing pins 164 and the code bar pins 166, a pair of slotted yokes 174 (FIGS. 29, 30, and 31) are positioned between the guide plate 165 and the shield 160. Each yoke 174 has a number of slots 175, each of which slips over two of the sensing pins 164 (FIG. 29). The edge of the slot 175 engages the shoulder of a head portion 176 of each pin, thus guiding the movement of the pin under the action of the spring 168.

Each yoke 174 is slidably mounted on a pair of studs 177 (FIGS. 29 and 30). A spring 178, mounted between the yoke 174 and the head of the stud 177, urges the yoke member leftwardly, as viewed in FIG. 30. It will be seen from this construction that, upon leftward movement of the yoke, both the sensing pins 164 and the code bar pins 166 are also released for movement in the same direction. Limiting this movement is a finger portion 360 (FIG. 29) of the bell crank 154, which normally is positioned adjacent the end of the sensing pin 164. When a positive fluid pressure signal is applied to any of the pistons 143 to 146 inclusive, the piston moves to the right, thus moving the lever 153 against the action of the spring 157 and rocking the bell crank 154 clockwise (FIG. 29), thereby moving the finger 360 out of its engaging position with the pin 164. If, at this time, the yokes 174 move to the left, both the sensing pins 164 and the code bar pins 166 also move to the left. As will be described hereinafter, this movement of the code bar pins allows the setting of an associated code plate for converting the binary digit, represented by the movement or lack of movement of the pistons 143 to 146 inclusive, to a decimal digit for controlling the printing mechanism.

Each of the yokes 174 is attached at its ends to a pair of lifter bars 179 (FIGS. 30 and 31), each of which in turn is attached to a pair of lifter arms 180, pinned to a shaft 181, rotatably supported on the cover 158. Also pinned to the shaft 181 is an arm 182 (FIGS. 30, 31, and 33), having a spring 183 mounted on its lower end for normally urging said arm counter-clockwise, as viewed in FIG. 33. The other end of the arm has rotatably mounted thereon a link 184, which is attached to a cam follower arm 185. The cam follower arm is rotatably mounted

on a shaft 186, located in the printing mechanism. The cam follower arm 185 is provided with a roller 187, which engages the cam surface of a cam 188, pinned to a cam shaft 189. The cam shaft 189 is the same drive shaft indicated as 312 in FIG. 4 of the United States patent to Guido Carnacina cited previously. This shaft is rocked first counter-clockwise and then clockwise during a machine operation, as disclosed in that patent. During the counter-clockwise movement of the cam 188, the arm 185 is similarly rocked in the same direction, thus rotating the arm 182 counter-clockwise. This movement of the arm 182 moves the yoke 174 towards the cover 158, allowing the sensing pins 164 to sense the position of its associated finger portion 360 of the bell crank 154.

Associated with the code bar pins 166 is the code bar assembly 190 (FIG. 29), slidably mounted between a pair of code bar plates 191, which are secured to the housing 37 by screws 192. There is one code bar plate and code bar assembly for each row of pistons 143 to 146 inclusive. Each assembly consists of five code slides 193 to 197 inclusive (FIG. 32), having a series of notches 198 on one of their edge surfaces. Four of the slides contain a pair of slots 199, each positioned over a stud 200, extending between the code bar plates 191. Each of the four slides also has a finger 201 on its upper end, over which is positioned a spring 202 (FIG. 29), the other end of which extends through an aperture located in a spring guide plate 203 against a support plate 204, mounted between the code bar plates 191. The plates 203 and 204 are mounted together by means of screws 205. The springs 202 normally urge each of their associated slides downwardly.

This downward movement of the slides is controlled by the engagement of a stop portion 206 (FIG. 32) of each of the four movable slides with one of the code bar pins 166 (FIG. 29). Thus the slide 193 engages the pin controlled by the piston 143, the slide 194 engages the pin controlled by the piston 144, the slide 196 engages the pin controlled by the piston 145, and the slide 197 engages the pin controlled by the piston 146. The slide 195 is rigidly mounted on the studs 200. It also has a stop portion 207, which coacts with a second stop portion 208 of each of the movable slides to limit the movement of each slide when it is released by the withdrawal of its associated code bar pin in the manner described previously.

From FIG. 32 it is seen that, upon the release of each slide, certain of the notches of each slide are in alignment. The aligned notches form a slot which positionally represents the decimal digit represented by the movement of the slide which is actuated by its associated binary piston. Thus, in reading out the digit "8," which is represented by a positive fluid pressure signal's being applied to the piston 146, only the slide 197 is moved downwardly, thus aligning the lowermost notches of each slide in the assembly. This forms a slot which positionally represents the digit "8." As shown in FIG. 32, the notches in the slide 195 positionally represent the digits 0 through 8, beginning with the top notch. Since the pins 166 are mounted in a straight line, each of the stop portions 206 and 208 of the slides has a bent-over tab end 209, thus allowing each slide to act independently.

In order to control the timing of the sensing movement of the code slides, there is mounted between the code bar plates 191 a second shaft 210 (FIG. 29 and 33). Pinned to the shaft 210 is a yoke 211, which engages the lower end of the movable slides 193, 194, 196, and 197. Also pinned to the shaft 210 is an actuating arm 212 (FIG. 33), the lower end of which is connected to a spring 213, normally urging the arm 212 clockwise. Rotatably mounted on the other end of the arm 212 is a link 214, which is connected to a cam follower arm 215 rotatably mounted on the shaft 186. The arm 215 has mounted thereon a roller 216, which engages the cam 188. Upon operation of the cam 188, the yoke 211 is rocked clockwise, releasing the slides for movement under the action of the springs 202. Depending on the pressure signals applied to the pistons

143 to 146 inclusive, those slides so actuated will move under the action of their springs 202 until their stop portions 203 engage the stop portion 207 of the slide 195. This results in the alignment of the series of notches 198 to form a slot which positionally represents the decimal digit generated by the logic packages in binary form during a machine operation.

Associated with the slides 193 to 197 inclusive is a sensing assembly 217 (FIG. 34) mounted on a differential member 218. This differential member 218 is indicated as 501 in FIG. 20 of the previously-cited Carnacina United States patent. The setting of the member 218 controls the printing mechanism to print the digit represented by the position of the member. Reference should be made to the above-cited Carnacina United States patent for a complete disclosure of this printing operation.

The sensing assembly 217 includes a support member 219, a sensing carriage 220, a wide sensing finger 221, and a spring 222 normally urging said carriage in a direction for sensing the notches 198 of the coded slides. The spring 222 is mounted on a number of studs 223 located on the differential member 218. The carriage 220 contains an oblong slot 224, in which is located a stud 225 mounted on the member 218. During a printing operation, the differential member 218 (FIG. 29) is first rotated counter-clockwise, thus wiping the sensing carriage along the coded slides 193 to 197 inclusive. Upon sensing the aligned notches, the sensing finger 221 moves into the slot under the action of the spring 222. This action rotates the carriage clockwise about the stud 225 until a tab 226 of the carriage engages the edge of the differential member 218, thereby stopping the differential member in a position representing the digit to be printed. After the printing operation has occurred, the differential member 218 is rocked clockwise, thus removing the sensing finger from engagement with the coded slides. After this has occurred, the cam 188 (FIG. 33) is rocked clockwise, thus rotating the yoke 211 counter-clockwise to restore the coded slides to their home position and rocking the arm 182 clockwise, thereby moving the sensing pins 164 and the code bar pins 166 to their home position.

While the coded slides 193 to 197 inclusive contain slots for positionally representing the digits 0 to 8 inclusive, the digit 9 also is printed. This position corresponds to the farthest position of travel of the differential member 218. Thus, when a 9 is to be printed, none of the notches 198 are in alignment, and the sensing carriage 220 sweeps past all of the notches in the coded slides 193 to 197 inclusive to a position controlled by the printing mechanism. This operation is fully disclosed in column 16 of the specification of the previously-cited Carnacina United States Patent, No. 2,905,382.

Referring to FIG. 2, there are shown, located at the top of the rear compartment of the calculating machine, the platen 227 and the supply roll 228 of paper for the platen. This construction is the same as that disclosed in the previously-cited Carnacina United States patent, and reference should be made to that patent for complete disclosure of this operation.

Referring now to FIG. 35, there are shown a diagrammatic representation of the various logic packages used in the calculator and their interconnecting relationship. FIG. 38 shows a diagrammatic layout of the various logic circuits that make up the control logic package, with their corresponding reference figure numbers. The binary-coded decimal system is utilized in the logic circuits, the binary bit "1" being represented by a positive (+) fluid pressure signal, while the binary bit "0" is represented by a negative (-) fluid pressure signal. The operation of the calculator will be disclosed by a description of the four basic operations performed by the calculator—namely, addition, subtraction, multiplication, and division—and operation of its control key. All relays which are indicated with a plus or minus signal applied to the input ports are so supplied with such signals from

the fluid supply system previously disclosed in relation to FIG. 2.

The logic packages indicated in FIG. 35 and also in FIG. 2 are composed of a plurality of relatively thin plates similar to those disclosed in FIGS. 25 to 28 inclusive of the indicator package. The plates are mounted in a horizontal plane and are assembled in the same manner as previously described in relation to the indicator and keyboard logic packages.

10

Addition

In the following description of the logic circuits, characterizing of a relay as in a negative condition describes a relay having a negative fluid pressure applied to its control port, while a positive condition refers to a positive fluid pressure applied to the control port. These same conditions also apply when a relay is referred to as being switched off or switched on, respectively. Also, the switching of a relay refers to the changing of the character of the fluid pressure at the control port.

20 In an adding operation, the digits of the first amount are entered into the calculator by use of the amount keys of the keyboard. Each digit entered is converted into a series of pressure signals representing its binary digit code and entered into the "K" register. The "K" register is connected to the keyboard indicator 22 (FIG. 1), which displays the entered number. The "Add" key 92 (FIG. 15) is then depressed, which adds the amount in the "K" register to the "A" register. Each succeeding number is entered in the same manner. The use of the "Add" key 92 also results in the printing of the number that is in the "K" register and also of a symbol which is representative of the control key being used in this operation. In this case, the symbol that is printed out on the audit strip is a plus sign.

30 Referring now to FIG. 37, there is shown a schematic diagram of the amount portion of the keyboard. Each of the amount keys 62a is represented as connected to the control port of an associated double relay of the type disclosed in FIG. 5. As disclosed previously, the depression of any of the amount keys 62a connects a positive pressure source to channels located in the keyboard logic package, the channels so connected being the inlet control port of its associated double relay. This results in the switching of the piston of the double relay. FIG. 37 shows the status of the relays before the actuation of the first amount key. A positive pressure signal is applied over the channel 229, while the four output relays 230 to 233 inclusive are in a negative condition with negative pressure signals at their output channels 234 to 237 inclusive. As will be described more fully hereinafter, the pressure signals supplied over the channel 229 are part of a keyboard lockout system which disables the zero amount key until after the first significant amount key has been actuated.

40 Assuming that the amount key 62a representing the digit "7" is depressed, this action switches a double relay 238 to a positive condition, thus supplying a positive pressure signal over the upper output port channel 239, 45 the signal being transferred from the relay 240 through each succeeding double relay of each lower amount key. As shown in FIG. 37, the keyboard is divided into two sections, the amount keys representing the digits "1" to "5" inclusive having the positive signal being supplied by the relay 241, while the remaining amount keys have their positive signal being supplied by the relay 240.

50 The positive pressure signal being applied over the channel 239 from the relay 238 switches a three-stacked relay 242a, 242b, and 242c, of the type disclosed in FIG. 8, to a positive condition. In this state, positive signal pressures are applied over the output channels 243a, 243b, and 243c, respectively. The output channel 243a supplies the positive pressure signal to the relay 244, which, being in a negative condition, transfers the pressure signal to the 70 control port of the output relay 230. The output chan-

75

nels 243b and 243c supply their positive pressure signal to control ports of the output relays 231 and 232, respectively. This results in the switching of the relays 230 to 232 inclusive to a positive condition, thus providing a positive pressure signal on the output channels 234 to 236 inclusive. These signals were supplied by the channel 229 and the channel 245 to the lower input ports of each of the output relays. At this time, the output relay 233 remains in a negative condition, thus supplying a negative pressure signal to the output channel 237. Since each of the channels 234 to 237 inclusive represents the binary weights 1, 2, 4, and 8, respectively, it will be seen that the output channels will have pressure signals representing the digit "7" in the binary code of 1-1-1.

This procedure can be applied to each of the remaining amount keys, and it will be seen that the digit of the key depressed will appear on the output channels of the relays 230 to 233 inclusive in its binary form.

An interlock system is present in the relay arrangement, so that, upon two amount keys being depressed simultaneously, only the lower-order amount key will be effective. Returning to the above example of the actuation of the No. 7 amount key, it will be seen that, upon the switching of the relay 238 to a positive condition, the lower output channel 247 of the relay is now supplied with a negative pressure from the lower input port of the relay. This negative pressure is supplied to the double relay of each higher order amount key, thus disabling each of said keys. Depression of the No. 9 amount key 62a along with the No. 7 amount key, for example, results in a negative pressure signal being transmitted over both output channels of its double relay 246, thus being ineffective to switch the relays 244a and 244b to a positive condition.

A second interlock is contained in the keyboard, which prevents the zero amount key 62a from being the first amount key to be effective. This feature is to assure that only digits which are significant will be recognized by a shift counter (FIGS. 40A and 40B) which controls the number of digits entered into the "K" register in a manner to be described hereinafter. This interlock is removed after an amount key other than the zero key has been actuated. It will be seen that the input channels 248 and 249 (FIG. 37) of the double relay 250 of the zero amount key are connected to the output channels of the relays 251 and 252, respectively. Before the actuation of an amount key, both of these channels carry a negative pressure. Upon the actuation of an amount key other than zero, the control channel 253 of the relay 251 is provided with a negative pressure signal in the manner described above, thus switching the relay to a negative condition. In this state, the relay provides a positive pressure signal on its output channel 254, this signal being supplied over the input channel 245 from the channel 229. This positive pressure signal is applied over the channels 248 to the relay 250, which, being in a negative condition, transmits the signal over its output channel 255 to the relay 256, thus switching the relay 256 to a positive condition. This results in the output of the relays 257 and 252 transmitting a positive pressure signal over the channels 249 to the relay 250, thus conditioning the zero amount key. Actuating of the key now switches the relay 241 to a positive condition, thus disabling each of the other amount keys and switching the relay 251 to a negative condition, as described above. The output channels 234 to 237 inclusive of the output relays 230 to 233 inclusive contain negative pressure signals representing the digit zero in binary form.

The output channels 234 to 237 inclusive are connected to the "K" register shown in FIG. 51. The register has a storage capacity of twelve digits, only the sections for storing three digits being shown in FIG. 51. The remaining nine storage sections are of the same construction and operate in the same manner as those disclosed. In order to limit the digits being entered into the register

so as not to overload its capacity, a shift counter is provided, which counts the number of digits being entered into the "K" register. This counter is shown in FIG. 40A. As described above, each time an amount key is depressed, the relay 251 (FIG. 37) is switched thereby, providing a positive pressure signal over the output channel 254. This signal functions as a clock signal and is turned off when the amount key is released. The positive signal over the channel 254 is introduced into a series of control flip-flops shown in FIG. 40C. The function of these flip-flops is to distinguish between the first clock cycle and each succeeding clock cycle, so as to reset the "K" register for each new amount keyboard operation. The positive pressure signal over the channel 254 is fed to the upper input port of the relay 258 (FIG. 40C), which at this time is in a negative condition. This positive pressure signal then is transmitted from the relay 258 to the control port of a three-stacked relay 259a, 259b, and 259c, each relay composing a part of a flip-flop. It will be seen that the relay 258 functions as an OR relay. Either a positive signal in the input channel 254 or a positive control signal in the control channel 285 produces a positive pressure signal in the output channel of the relay 258. As will be described hereinafter, this latter condition occurs when a control key is actuated. The first flip-flop is composed of the relays 259a, 260a, 261a, and 261b. The second flip-flop is composed of the relays 259b, 260b, 262a, and 262b. The third flip-flop is composed of relays 259c and 263b. Switching of the relay 259a to a positive condition sets the flip-flop so that the relays 260a and 261a are negative. The control ports of the relays 261a and 261b are supplied with a negative control pressure over the channel 280. This control signal is negative when the amount keyboard is being used and positive when a control key is depressed to initiate a machine operation, as will be described more fully hereinafter. This signal is used to reset the flip-flops. A negative pressure occurs on the output channels of the relays 261a and 260a as a result of this condition. It will be seen by inspection that the flip-flop is now in a stable state.

The second flip-flop has the relays 259b and 262b in a positive condition, while the relays 260b and 262a are in a negative condition. With this arrangement, a positive pressure signal is supplied from the output channel of the relay 262b to the upper input port of the third flip-flop. This has no effect on the output of relay 259c, since the relay is in a positive condition. The other relays 262c and 263a of this flip-flop are at this time in a negative condition, thereby providing a stable condition for the flip-flop. With the relays 261a and 263a in a negative condition, the pressure signal being conducted to the control port of the relay 257a is derived from the output of the relay 260a. Thus the relays 257a and 257b are in a negative condition at this time. As a result, a negative pressure is applied over the output channel 264 of the relay 257a, and a positive pressure is applied over the output channel 281 of the relay 257b.

Upon release of the amount key 62a (FIG. 37), the relay 251 is switched back to its home position, thus supplying a negative pressure signal over the output channel 254. If a clock signal over the channel 285 had conditioned this circuit for operation, this effect would be the same when the clock signal was removed. The application of this signal to the control ports of the relays 259a, 259b, and 259c (FIG. 40C) through the relay 258 does not affect the condition of the first two flip-flops described above, even though the relays 259a and 259b are switched. Switching of the relay 259c results in the application of a positive pressure signal at its lower input port, derived from the relay 262b to the upper input port of the relays 259c and 262c, to the control port of the double-stacked relays 263a and 263b. The relay 262c is in a negative condition due to the signal from the relay 260c. Switching of the relay 263b to a positive condition

supplies a positive pressure signal, derived from the relay 261c, to the control port of the double-stacked relays 257a and 257b. Switching the relay 257a to a positive position supplies a positive pressure signal over the channel 264, which acts as a clock signal when applied to the shift counter (FIG. 40B), to be described hereinafter. The switching of the relay 257b at this time switches the signal being applied over the channel 281 from a positive condition to a negative condition. This signal also acts as a clock signal which is utilized in a manner to be described hereinafter. The switching of the relay 257a to provide a positive pressure signal instead of a negative pressure signal will indicate, in a manner to be described hereinafter, to the counter that the amount key operation is the initial key operation. Any subsequent changing of the signal over the channel 254 or 285 does not affect the state of the relays 257a and 257b. This is due to the fact that the third flip-flop with the relay 259c is now in a positive stable state. Any switching of this relay does not affect the output of the relay. Only when a positive signal is applied over the channel 280 will the flip-flops be reset.

The switching of the signal in the output channel 264 of the relay 257a is fed into the shift counter shown in FIG. 40B. As mentioned previously, the counter controls the number of amount key operations that can be entered into the "K" register. The counter consists essentially of four double-acting relays 276, 277, 278, and 279, which store a binary-coded digit representing the number of amount keys entered since the last operation of the calculator. Each of the relays 276, 277, 278, and 279 is controlled by a clock signal derived from FIG. 46C over a channel 273 in a manner to be described presently. This control signal is "on" when an amount key is depressed and "off" when the amount key is released.

Upon the depression of an amount key, the positive pressure signal applied over the output channel 254 of the relay 251 (FIG. 37) is fed to the control port of a two-stacked relay 268a and 268b (FIG. 46C). The switching of the relay 268a provides a positive signal over the output channel 269 to the control port of a double-acting relay 270, thereby switching this relay to a positive condition. As will be described more fully hereinafter, the switching of the signals in the output channels 271, 272 of the relay 270 actuates the "K" register to accept for storage the digits sent from the amount keyboard. The switching of the relay 268b to a positive condition provides a positive signal in its output channel 273 (FIG. 46C), which signal is transmitted to the shift counter (FIG. 40A). This signal switches two four-stacked relays 274a, 274b, 274c, and 274d and 275a, 275b, 275c, and 275d. As will be described more fully hereinafter, the switching of these relays transfers a binary digit representing the next highest amount key to the relays 276, 277, 278, and 279. These relays, together with the relays 288a, 288b, 288c, and 288d constitute input and memory flip-flops.

Assuming at this time that the relays 276, 277, 278, and 279 are in a condition which represents the number of amount key operations of the last amount operation, the first amount key depressed in a new amount operation supplies a positive pressure signal over the channel 273 and a negative signal over the channel 264 in the manner just described. Taking the first binary bit section as an example, the relays 265c, 267a, and 284a (FIG. 40B) being at this time in a negative condition, the switching of the relays 274a, 274b, 274c, and 274d and 275a, 275b, 275c, and 275d by the signal in the channel 273 provides the output of the relay 274b with a negative signal derived from the relay 288a. The relays 274a and 288a constitute an input flip-flop, while the relays 274b and 276 constitute the memory flip-flop. The switching of the relays 274a and 274b transfers part of a binary number stored in the input flip-flop to the memory flip-flop. The input flip-flop is then free to accept a new number. The

signal transferred to the memory flip-flop orients the relay 276 to a negative condition, thus representing the binary bit "0" of the digit "4." The relays 277 and 279 are similarly orientated, while the relay 278 is in a positive condition. The addition of the factor "three" to the shift counter upon the occurrence of the first amount key operation provides a simple arrangement of the shift counter to occur when the twelfth amount key is depressed. At that time, the memory relays 276 to 279 inclusive are all in a positive condition, thus representing the digit "fifteen." As will be described hereinafter, this condition produces a positive pressure signal in the output channel 286 (FIG. 40A) of the relay 302a. The upper output channel 289 of the relay 276 has a negative signal, while the lower channel 283 has a positive pressure signal. Both of these channels are connected to the relay 290a of a four-stacked relay which includes the relays 290a, 290b, 290c, and 290d. The relays have their control port connected to a channel 291, over which a control signal is applied during other operations of the calculator. This signal, as will be described hereinafter, controls the operation of the "K" and "M" registers and will countdown the digits stored in the relays 276 to 279 inclusive. The signal is "off" when an amount key is depressed. The output channel 292 of the relay 290a transmits the negative signal to the control port of the relay 293 of the next binary bit section. This signal controls the output relay 294. The output signal from the relay 294 is then fed to the lower input port of the relay 267b of the next binary bit section.

Upon release of the amount key of the first key operation, a negative pressure is applied over the channel 273, due to the switching of the relay 268b (FIG. 46C) and a positive pressure signal over the channel 264, the latter signal being transferred to the control port of the four-stacked relay 267a to 267d inclusive through the relay 265c. The turning on of these relays connects their lower input port to the output ports of the counter. In the case of the relay 267a, the lower input port is connected to the lower output channel 283 of the storage relay 276 over the channel 282. At this time, the signal is positive. This signal is transferred through the relays 284a, 274a to the control port of the relay 288a, which is switched to provide a positive pressure signal on its output. Thus the next highest number is stored in the input flip-flop. This number is then transferred to the memory flip-flop upon the depression of the next amount key by the application of a positive pressure signal over the channel 273 to the control ports of the relays 274a to 274d inclusive. The positive pressure signal of the instant example is transferred to the control port of the relay 276, thereby orientating said relay to a positive condition, which represents the binary bit "1." Thus the digit "5" is represented by the orientation of the relays 276 to 279 inclusive at the end of the second key operation of the calculator.

Since the control pressure signal over the channel 264 remains positive during the remaining amount key operations, the signals derived from the relay 294 (FIG. 40A) and also from the relays 295 and 296 of the other binary bit sections are transferred to the lower inputs of the relays 274b, 274d, 275b, and 276d during each succeeding operation, these signals representing the next highest number. Each of the signals is controlled by the carry signal of the preceding binary bit section.

In the operation just described, the carry signal being fed over the output channel 292 (FIG. 40A) of the relay 290a to the relay 293 is also fed over the channel 297 to the lower input port of a carry transfer relay 298. It will be seen by inspection that a positive carry signal can be transferred from the relay 298 through the relays 299b, 300, 302, and 302a. This occurs when all of the relays 276 to 279 inclusive are positive, thus representing the capacity of the "K" register. All of the output relays 293 to 296 inclusive are negative at this time. The output

of the last transfer relay 302a is positive under these conditions. This signal is transmitted over the channel 286 to the lower input port of a relay 303, which is "on" due to the positive signals being applied from the channel 264 through the relay 265c over the channels 266 and 304. The positive pressure signal is transferred from the relay 303 to the control port of the relay 305, which turns on the relay 305. The turning on of the relay 305 supplies a negative pressure signal to the control port of the relay 306, which results in the conducting of a negative pressure signal over the output channel 229 of the relay 306. This negative pressure signal is transferred to the amount keyboard (FIG. 37), which cuts off any transmission of positive signals over the output channels 234 to 237 inclusive. Thus it is seen that the amount keyboard is unable to transmit any other digits into the "K" register.

Referring now to FIG. 51, there are disclosed three stages of the twelve-stage "K" register. Each stage functions in the same manner. Located on the right side of the drawing are shown the four input channels 234 to 237 inclusive, over which the digit in binary form is transmitted from the amount keyboard, as described previously. At this time, the amount key has been depressed. Two clock pulses over channels 271 and 272 (FIGS. 46C and 51) have been switched, with the positive signal on channel 271 and the negative signal on channel 272. A negative pressure signal for resetting the last eleven stages of the "K" register is also generated over the channel 308 at this time upon the release of the first amount key. Referring again to FIGS. 40A, 40B, and 40C, it will be seen that the signal transmitted over the channel 264, through the relay 265c, over the channels 266, 304 to the control portion of the relay 307, will switch the relay to turn on the booster relay 307a to provide the same signal over the output channel 308. As disclosed previously, this signal becomes negative at the end of a machine operation and becomes positive when the amount key is released. This switching of the signal resets each of the last eleven stages of the "K" register to a negative condition.

The first stage of the "K" register is reset by depression of the Clear key 83 (FIG. 15). This key is normally used in those cases where the wrong amount key has been depressed. Depression of the Clear key 83 (FIG. 36) provides a positive pressure signal over the channel 628 (FIG. 40B), which turns on the relays 265a and 265b, thereby switching the signal being transmitted over the channel 310 to the first stage of the "K" register from a positive signal to a negative signal. This operation then resets the first stage in a manner to be described hereinafter. Upon release of the Clear key 83, the relays 265a and 265b are switched, thus supplying a positive pressure over the channel 310.

Another control signal is transmitted over the channel 291 (FIG. 51), which controls each stage of the register. As will be described more fully hereinafter, this signal is normally negative until a multiplication operation or a division operation occurs, during which time the signal (FIG. 42B) is switched to a positive condition. This positive pressure signal controls the shifting of the digits stored in each stage of the register to the next stage on the right, and, as described previously, controls the shift counter (FIG. 40A) to downcount by "one" the number stored in the counter.

Each binary bit section of each stage of the "K" register comprises a pair of flip-flops. The first set of flip-flops of each bit section is composed of one of the relays 311a to 311d inclusive and 312a to 312d inclusive (FIG. 51) and is characterized as the input flip-flop. The second set of flip-flops of each bit section is composed of one of the relays 313a to 313d inclusive and the second relay 315a to 315d inclusive of the double-acting relay comprising relays 314a to 314d inclusive and 315a to 315d inclusive. This latter set is characterized as a memory flip-flop. Taking the example disclosed previously, the depression

of the amount key representing the digit "7" has produced positive pressure signals over the channels 234 to 236 inclusive and a negative pressure signal over the channel 237. With the depression of the first amount key, the relay 270 (FIG. 46C) is switched. Thus appears a positive pressure signal in channel 271 and a negative signal in channel 272. A positive pressure signal is in channel 310, and a negative pressure signal in channel 291 and in channel 308. A positive pressure signal representing the binary bit "1" is fed into the upper input port of the relay 316a, which is part of a four-stacked relay of the type shown in FIG. 9. Since the relay is "off" at this time, the signal is transmitted over channel 317a to the control port of the relay 311a, turning the relay "on." Since the lower input of the relay 311a is connected to the channel 310, a positive pressure signal is transmitted to the relay 312a, turning the relay "on." With a positive pressure signal being transmitted over the channels 271 to the lower input port of the relay 312a, the input flip-flop is set positive, with a positive signal being applied over the channel 317b to the control port of the relay 313a. The relay 313a is turned "on" to transmit a positive signal derived from channel 310 to relay 314a, thus producing a positive pressure signal on the output channel 318a, representing the binary bit "1."

Each of the output channels 318a to 318d inclusive, representing in binary form the digit stored in the first stage of the register, is connected to the channel 139 (FIG. 14) of the first stage of the keyboard indicator 22 (FIG. 1). At this time, the control relay 140 is turned "on" to allow the associated indicator piston of the keyboard indicator to be actuated in the manner described previously. As will be described hereinafter, the control relay 140 is turned "off" upon the actuation of a control key. Each stage of the "K" register has its output channels 318a to 318d inclusive connected to a corresponding stage of the keyboard indicator. Thus the digit entered into the "K" register is also set up in the keyboard indicator.

The turning "on" of the relay 314a turns on the relay 315a, thereby conducting the negative pressure signal being transmitted over the channel 272. The negative output of this relay is fed over the channel 319 to the control relay 320a of the next stage. Upon release of the amount key, the signal over the channels 272 and 308 is switched to a positive signal, while the signal applied over channel 271 becomes negative. This resets the input flip-flop of the first bit section to a negative condition while setting the memory flip-flop to a positive condition. Thus the output channel of the relay 315a has a positive pressure signal, which is transmitted to the upper input port of the relay 320a of the second stage of the register. At this time, the relay 320a is in a negative, or "off," position. This relay transmits the positive pressure signal to the control port of the relay 321, thereby turning the relay "on." With a positive pressure signal being applied to the lower input port of the relay 321 from the channel 308, this signal is transmitted to the relay 322 to condition the relay positively. With a negative pressure signal being applied to the lower input port of the relay 322 from the channel 271, it is seen that a negative pressure is on the output channel of the relay. Thus, upon the depression of the next amount key, when the channel 271 switches from a negative pressure control signal to a positive pressure control signal, the positive signal stored in the memory flip-flop of the first stage is transferred to the input flip-flop of the second stage. Upon release of the second amount key, the digit of the first amount key is stored in the memory flip-flop composed of the relays 323 and 324b, of the second stage, while the memory flip-flop of the first stage contains the digits of the second amount key that was depressed. With depression of each succeeding amount key that is required, the digits are transferred and stored in the register in the manner just described.

As will be described more fully hereinafter, the output channels 318a to 318d inclusive of each stage of the register are also connected to the selector package unit disclosed in FIG. 48. From this unit, the amount stored in the "K" register is transmitted to the binary conversion unit 38 (FIG. 2) and to the adder (FIGS. 49A and 49B). In the binary conversion unit, the pressure signals control the pistons 143 to 146 inclusive, so that the amount in the "K" register is printed upon initiation of a printing operation. The transfer of the amount to the adder results in the amount's being added to the amount in the "A" register. This occurs when the appropriate control key is depressed, thereby entering the sum in the "A" register.

A novel feature of this calculator is the automatic retention of a number in the register after a machine operation has occurred. This feature is a by-product of the reset signal generated in the relay 307a (FIG. 40A) over the channel 308. As explained above, the "K" register is reset upon the entering of the first amount digit in the register. This occurs when the signal in the channel 308 is negative at the time the clock signals over the channels 271 and 272 are switched in a manner described previously. Thereafter, the signal over the channel 308 is positive during the remaining keyboard operation, thereby preventing the clearing of the number from the "K" register. Thus the amount in the "K" register may be utilized, as will be explained more fully hereinafter, by any number of control keys in as many machine operations. Only when a new amount is entered will the "K" register be cleared.

At the end of an amount key operation with the amount entered into the "K" register, the "Add" key 92 (FIG. 15) is depressed. As will now be explained, the depression of the "Add" control key results in the initiation of a printing operation, whereby the amount in the "K" register is printed, and in the storing in the "A" register of the sum of the amounts in the "K" register and in the "A" register. A symbol representing the "Add" control key is printed also.

Referring to FIG. 36, there is shown a schematic drawing of the control section of the keyboard. It is seen that the construction and the operation of the control keyboard are the same as the construction and the operation of the amount keyboard; namely, each control key, when depressed, generates a binary digit which is transmitted over the output channels 325 to 328 inclusive. The channels 325 to 328 inclusive represent the binary weights 1, 2, 4, and 8, respectively. The numerals indicated above each control key represent the digit which is generated in binary code over the output channels when that control key is depressed. In the present example, the binary digit "4" is generated with a positive pressure signal generated by the relay 329 over the output channel 327, while the remaining channels transmit negative pressure signals. The actuation of the control key 92 turns "on" the relay 329, thereby selecting the lower input channel 330. This channel is connected to a control channel 331, which at this time is conducting a positive signal. This positive signal is generated from a relay 349 (FIG. 42B). As will now be described, the actuation of a control key results in the switching of the relay 349 to provide a negative signal to the control keyboard, thus disabling the remaining control keys.

As shown in FIG. 42A, the output signals over the channels 325 to 328 inclusive are each fed into the control port of a relay which is part of the memory flip-flop. The positive pressure signals being applied over the channel 327 switch on the relays 333a to 333d inclusive. The switching of the relays 333a to 333d inclusive provides a positive signal to the control port of the relay 334, thereby switching the relay to provide a positive signal in its output channel 335. This positive signal is derived from the relay 332 (FIG. 42B), in a manner to be described hereinafter, over the channels 280, 336 (FIGS. 42A and

42B), and 337 to the lower input port of the relay 334. It will be seen that the output of this flip-flop is the same as the signal applied over the input channel 327. Each of the other flip-flops associated with the remaining output channels will be set accordingly. Thus the binary digit is stored in the flip-flop associated with the input channels 325 to 328 inclusive, thereby acting as a memory of what control operation is occurring. This allows the particular control key to be released without disrupting the control signals.

Switching of the relay 333b provides a positive signal on its output channel 338, which, in this add operation, is transmitted to the relays 339b, 340b to the relay 341, which is switched to provide a positive signal over its output channel 342 (FIGS. 42A and 42B) to the upper input port of the relay 343. At this time, the relay 343 is "off," thereby transmitting the positive pressure signal to the control port of a relay 344, which is part of a flip-flop circuit composed of the relays 344, 345, and 346.

The relay 345 is in a negative condition at this time. With the positive pressure signal being applied at its upper input port from the relay 344, the relay 345 transmits this signal to the relay 346. It will be seen that this signal will switch the relay 346 to provide a positive signal on its output channel 347, which is transmitted to the upper input port of the relay 344. This turns the flip-flop "on," and the flip-flop will stay "on," supplying a positive signal as long as the pressure signals in the control port of the relay 345 stay negative.

The positive pressure signal output of the flip-flop being applied over the channel 347 is transmitted to three relays, 332, 348, and 349, thereby switching each of these relays to a positive condition. Switching of the relay 332 provides a positive pressure signal in its output channel 280. This signal, as disclosed earlier in relation to an amount key (FIGS. 40A, 40B, and 40C) operation, conditions the control flip-flops shown in FIG. 40C to be reset upon the generation of a clock signal over the channel 285. The clock circuit (FIG. 39) which generates the clock signal over the channel 285 is turned "on" by the positive pressure signal in channel 280 in a manner to be described hereinafter.

The positive pressure signal being applied over the output channel 280 is also transmitted over the channel 336 to the lower input port of the relay 334, which turns "on" the control flip-flop associated with the channel 327 in the manner described previously. It can be seen that this positive signal in the channel 336 is applied in the same manner to the control flip-flops of the other binary bit sections.

Switching of the relays 348 and 349 (FIG. 42B) provides negative control signals on their output channels 315 and 331, respectively. The channel 331 is connected to the control keyboard (FIG. 36), as described previously. It will be seen that the switching of the signal in the channel 331 from a positive pressure to a negative pressure will prevent any other control key from being activated in the manner described in connection with the amount keyboard. The negative signal being transmitted over the channel 350 from the relay 348 will be used in a manner to be described hereinafter.

The turning on of the control flip-flop associated with channel 327 (FIG. 42A) by the control signal in channel 336 results in a positive pressure signal's being applied to the control port of the relay 352, which will be switched on to provide a positive pressure signal on its output channel 355. Since the other binary bit sections are similarly arranged, it will be seen that the output channels 353 to 356 inclusive will transmit the same binary digit as contained on the input channels 325 to 328 inclusive, previously described.

Each of the output channels 353 to 356 inclusive is connected to a series of relays 357, 358, and 359 (FIG. 44). With the present example, a positive pressure signal is applied over the input channel 355, while the re-

maining channels provide negative pressure signals. The positive pressure signal over channel 355 turns on the relay 358, which transmits a negative signal over its output channel 360. This signal does not affect the relays 361a and 361b or 362. Thus the outputs of these relays will remain the same. The function of these relays is to identify the type of control operation that is occurring. As will be explained more fully hereinafter, when a multiplication operation or a division operation occurs, positive control signals are generated by these relays for controlling other parts of the logic packages.

The output channel 363 of the relay 362 is connected to a control relay 364 (FIG. 42B), which is associated with a delay circuit composed of three flip-flops, 365, 366, and 367, constituting a shift register. This delay circuit controls the switching of the control relays 332, 348, and 349 to their negative, or "off," position. The operation of this circuit will be described hereinafter.

As disclosed previously, the switching of the relay 332 (FIG. 42B) to a positive position provides a positive pressure signal over its output channel 280. This signal is transmitted over the channel 280 to a clock circuit, shown in FIG. 39, the channel 280 being connected to the control port of the relay 369. At this time, the lower input of the relay 369 has a positive pressure signal applied thereto. The output channel 370 of the relay 369 is applied to a relay 371, which, when turned on by the positive signal in channel 370, will turn on a relay 372d, which is part of a four-stacked relay of the type disclosed in FIG. 9. There are seventeen four-stacked relays, 372 to 388 inclusive, which are used in this clock generating pulse circuit. These relays constitute sixteen flip-flops, twelve of which are indicated in FIG. 39. The flip-flops 9 to 12 inclusive are left out, as indicated by the dotted line 389, since their operation is the same as that of the other flip-flops.

The switching of the relays 372a to 372d inclusive to a positive condition provides positive pressure signals in the output channels of the relays 372a, 372b, and 372d, and a negative pressure signal in the relay 372c. The positive signal from the relay 372a is transmitted to the upper input port of the relay 390, which at this time is turned off. The relay 390 transmits the positive pressure signal to the relay 391c, which is one section of a three-stacked relay of the type shown in FIG. 8. Turning on of the relays 391a, 391b, and 391c results in a positive pressure signal's being transmitted over the output channel 285 from the relay 391a. This signal is a clock signal and controls several operations, as will be disclosed hereinafter.

With the turning on of the clock signal, the relay 372b turns on the next relay 373d in a manner to be described hereinafter. This operation continues consecutively through each succeeding relay, as indicated by the numerical order of the relays. When the relay 377a is turned on, a positive signal is applied to the control port of the relay 390, which turns on the relay, so that a negative pressure signal is applied to the relay 391a, thus turning off the clock pulse. Each succeeding flip-flop is turned on, as a result of a flip-flop already actuated being turned off. This resetting operation occurs when the relay 372d is turned on. A positive pressure signal is applied over the channel 393 from the relay 372d to the relay 394, thereby turning on the relay, which results in a positive pressure's being transmitted to the upper input port of the relay 387b. At this time, the relay is turned off, thereby allowing the positive pressure signal to turn on the relay 388c. The switching of the relay 388c supplies a positive pressure signal through the lower input port of the relay 372b, which is now turned on, to the control port of the relay 373d, thereby turning on the relay and the flip-flop of which it is a part. The switching of the relay 388c also turns on the relay 388b, which turns off the positive signal being applied through the relay 369 over the channel 370 to the relay

75

371. At this time, the relay 373a has been turned on, thus providing a negative pressure signal to the upper input port of the relay 371. This signal is then applied to the relay 372d, thus resetting the flip-flop.

In the next flip-flop, the relay 372c has been turned off at this time, thereby supplying a positive pressure signal to the relay 373b. With the relay 373b turned on at this time, the positive signal from the relay 373b will turn on the relay 374d. Thus each succeeding flip-flop will be alternately turned on and then turned off. When the last flip-flop is turned on, with the relay 387a being moved to a positive position, the relay 387b will be turned on to provide a negative pressure to the control port of the relay 388c. This signal turns off the relay 388c and also the relay 388b, thereby providing a positive pressure signal to the lower input port of the relay 369. Since the relay 369 is turned on at this time, due to the fact that the control signal in the channel 280 is still positive, the operation of the circuit is repeated, with the second clock pulse being generated over channel 285. It will be seen from this arrangement that, as long as the control signal in channel 280 remains positive, clock signals will be generated from the circuit.

As explained previously, in order to control the number of clock pulses which are required for each control operation, a delay circuit is provided in FIG. 42B for turning off the relays 332, 348, and 349. As disclosed previously, the depression of the "Add" control key 92 results in a negative pressure signal's being applied over channel 363 (FIG. 44), which controls the relay 364 (FIG. 42B) to provide a positive pressure signal to the upper output port of the relay 396a. Also the turning on of the relay 332 (FIG. 42B) provides a positive pressure signal applied over the channel 368, which turns on the relays 395a, 395b, and 395c. Each of the flip-flops 365, 366, and 367 (FIG. 42B) comprises a shift register. When the first positive clock pulse is transmitted over the channel 285, the first flip-flop, comprising the relays 396a, 395a, and 365, will be held on. When the clock pulse is turned off, a second flip-flop, comprising the relays 396b, 395b and 366, will be held on, while the first flip-flop will be turned off. When the second positive clock pulse occurs, the third flip-flop, comprising the relays 396c, 395c, and 367 will be held on. The output of this flip-flop is transmitted to the lower input port of the relay 396d which at this time is turned on. This positive signal will be transmitted by the relay 396d to the control port of the relay 345, thereby turning on the relay. Switching of the relay 345 turns off the relay 346, which in turn turns off the relays 332, 348, and 349. The turning off of the relay 332 turns off the clock circuit disclosed in FIG. 39, while the positive pressure signal being applied over the channel 331 resets the control keyboard (FIG. 36) for subsequent control operation.

As part of the "Add" control key operation, the amount stored in the "K" register is transferred and added to the amount in the "A" register. Also the amount in the "K" register is printed. This latter operation occurs upon operation of the clock circuit just described. The positive pressure signal representing the clock signal in channel 285 (FIG. 39) is transmitted to the lower input port of a relay 397 (FIG. 43). At this time, the relay is turned on, due to a positive pressure signal originating in the relay 398, which is transmitted through the relay 399 to the control port of the relay 397. Both relays 398 and 399 are turned on at this time. The relay 399 is operated by the control signal generated during an amount keyboard operation (FIG. 40C), described previously. This signal is positive when the amount keyboard is not being used and is transmitted over channel 281 (FIGS. 40C and 43).

The relay 398 is operated by three relays 400a, 401, and 402 (FIG. 43). The relays 400a and 401 are operated by the control signals over the channels 355 and 356, which represent the last two binary bits of the control key

digit generated in FIG. 42A. With the "Add" key being depressed, a positive signal is transmitted over channel 355 and a negative signal in channel 356, as previously disclosed. This results in a negative pressure signal's being applied to the lower input port of the relay 402. This relay, which is controlled by the Mode key 84 (FIG. 36), is turned off, due to the negative pressure signal's being applied over channel 403 (FIGS. 36 and 43) as a result of the Mode key's not being depressed at this time. Thus a positive signal is applied from the upper input port of the relay 402 to turn on the relay 398.

The clock signal in channel 285, which is connected to the lower input port of the relay 397, is transmitted by the relay 397 to a printer switch 404, located in the rear portion of the calculator shown in FIG. 2. This switch is similar to the switch indicated as 279 in FIGS. 34 and 35 of the previously-cited Carnacina United States Patent No. 2,905,382. The closing of the switch 404 results in the energization of a pair of solenoids (not shown) over lines 405 and 406, thereby initiating an operation of the printing mechanism.

At the beginning of a printing operation, the rows of pistons 143 to 146 inclusive (FIG. 29) in the binary conversion unit 38 will have been set to represent the amount contained in the "K" register and two symbols representing the control key depressed. This occurred upon release of the amount key and the initiation of a control key operation, which will now be described. As disclosed previously in relation to the operation of the "K" register shown in FIG. 51, the output channels 318a to 318d inclusive of each digit section will constantly conduct pressure signals representing the digits stored in that section. These output channels are connected to the selector package, as indicated in FIG. 48. The selector package consists of thirteen digit sections, two sections being disclosed in FIG. 48. Twelve of the sections are of the same construction. One of these is shown in FIG. 48 and includes the four binary output relays 407a to 407d inclusive. The thirteenth digit section is shown having the binary output relays 408a to 408d inclusive. Each of the input channels 318a to 318d inclusive from the "K" register is fed into the middle input port of a pair of double-stacked double relays 409a to 409d inclusive. As will be described hereinafter, the other two input channels 415a to 415d inclusive and 416a to 416d inclusive are connected to the "A" and "M" registers, respectively.

The relays in the selector package (FIG. 48) are shown controlled by pressure signals transmitted over the control channels 410 and 411. The output channels 412a to 412d inclusive of the relays 407a to 407d inclusive are connected to the pistons 143 to 146 inclusive (FIG. 29) of the binary conversion unit, which controls the printing mechanism in the manner described previously. The output channels 413a to 413d and 414a to 414d inclusive of the relays 409a to 409d inclusive are connected to the adder (FIGS. 49A and 49B) and the "M" register (FIG. 50), respectively. Thus the signal over the control channels 411 can control the transfer of information from the "M" register, the "A" register, and the "K" register to the "Adder" and the "M" register. Each of the output channels 413 and 414 is connected to the input ports of the relay 407 over channels 419 and 420, respectively. It will be readily seen from this arrangement that, depending on the type of control signals that are transmitted over the control channels 410 and 411, the digits that are stored in the "K," "M" and "A" registers may be transmitted over the output channel 412 for printing of the stored information by the printer.

Assuming that the input channels 318a to 318d inclusive, which are connected to the "K" register, are at this time transmitting the digit "7" to the selector unit, a positive pressure signal on the input channels 318a to 318c inclusive produces corresponding positive pressure signals in the output channels 413a to 413c inclusive of

the relay 409. At this time during an adding operation, both control channels 410 and 411 will be conducting negative pressure signals, thereby turning off the relays 407a to 407d inclusive, 408a to 408d inclusive, and 409a to 409d inclusive. A negative pressure signal is in channels 415a to 415d inclusive, thus turning off the relays 417a to 417d inclusive, which provides a positive pressure signal to the lower input port of the relays 409a to 409d inclusive over the channel 418a and also to the "A" indicator 24 (FIG. 1) over the channel 418. Thus, when a positive pressure signal is applied over the input channel 318, the output channels 413 and 414 of the relay 409 will conduct positive pressure signals. These positive pressure signals are transmitted over channels 419 and 420 to the relay 407. Thus a positive pressure signal is conducted over the output channels 412 of the relay 407, which actuates the corresponding piston 143 to 146 (FIG. 29) to set its associated code bar 166 as part of a code-converting operation whereby the binary digit represented by the pressure signals over channels 318a to 318d inclusive will control the printing mechanism to print out its decimal equivalent.

Referring now to FIGS. 45A, 45B, 46B, and 46C, there are shown the four input channels 353 to 356 inclusive, which carry the binary digit representing the control key depressed, as previously described with respect to FIG. 42A. As shown in FIGS. 45A and 45B, each of the input channels 353 to 356 inclusive controls either a relay or a stacked relay. Thus the channel 353 controls the four-stacked relay 421a to 421d inclusive, the channel 354 controls the three-stacked relay 422a to 422c inclusive, the channel 355 controls the two-stacked relay 423a and 423b, and the channel 356 controls the relay 424. These relays help to control the type of pressure signals that appear in the output channels 425b and 425c (FIG. 45B) and channel 426a to 426d inclusive. In FIG. 46C, the input channel 354 is connected to the control port of the relay 427a, whose output channel 428 is tapped by the channel 429 (FIGS. 46B and 46C), which is connected to the upper input port of the relay 432b (FIG. 46B). The output channel of the relay 432b is channel 425a.

The input channel 354 to the relays 427a, 427b, and 427c is tapped by channel 431 (FIGS. 46B and 46C), which is connected to the relay 432a (FIG. 46B), whose output channel is 425d. The output channels 425a to 425d inclusive are connected to the row of pistons 143 to 146 of the conversion unit (FIG. 29) for controlling the printer to position a platen having the proper symbol type fonts. The output channels 426a to 426d inclusive (FIG. 45B) are similarly connected to a second row of pistons 143 to 146 inclusive. With this arrangement, each control key of the keyboard (FIG. 36) generates a pressure signal over the eight output channels 425a to 425d and 426a to 426d inclusive, which controls the setting of a pair of printing platens to print out a symbol or a pair of symbols which are representative of the control key depressed. In the present example, for the positive pressure signal in channel 355 and negative pressure signals in channels 353, 354, and 356, negative pressure signals are generated in the output channels 425a and 425d (FIGS. 46B and 46C) and 426a, 426b, and 426d (FIG. 45B), while positive pressure signals are generated in channels 425b, 425c, and 426c. These control signals control the printer to print out a plus symbol on the paper roll.

As disclosed previously, pressure signals representing the digit "7" are transferred from the "K" register to the selector unit (FIG. 48) over channels 318a to 318d inclusive upon release of the amount key. In addition to generating signals over the output channels 412a to 412d inclusive for transmittal to the printer, signals are generated over the output channels 413a to 413d inclusive, representing the digit being transferred from the "K" register. In the present example, the digit "7" will appear

in the output channels 413a to 413d inclusive, which are connected to the adder disclosed in FIGS. 49A and 49B and the operation of which will now be described.

The adder shown in FIGS. 49A and 49B is full parallel binary coded decimal adder-substracter. It consists of thirteen digit stages, three of which are shown in the drawings. Twelve of the stages are full adders, two of which are shown in FIG. 49B. In these stages, the number stored in the "K" or "M" register is added to or subtracted from the amount in the "A" register. Shown in FIG. 49A are the thirteenth stage and the sign logic circuits which control the sign of the sum of the adder and which distinguish between an adding operation or a subtraction operation so as to control the adder to perform the proper operation.

Since the adder portion of each stage operates in a pure binary form, while the input and output signals used in the calculator are in a binary coded decimal form, a factor of "six" is automatically added to each digit transferred to each stage from the "K" or "M" register. If a carry signal is generated as a result of the operation of the adder, the factor "six" is not subtracted from the sum of the operation. The lack of a carry signal indicates that the sum of the two digits was equal to "10" or more. If no carry signal is generated, the factor "six" is automatically subtracted from the sum. Both of these operations produce a result that is in binary coded decimal form.

Referring now to FIG. 49B, and assuming that the first digit in the "A" register is "0," the digit "7" stored in the first digit section of the "K" register is added to the digit stored in the first section of the "A" register. As disclosed above, the digit "7" is transferred from the "K" register to the selector logic package (FIG. 48), from which it is transferred to the adder over channels 413a to 413d inclusive. This operation occurs upon depression of the amount key. Also connected to the adder is the output of the "A" register (FIG. 52). The "A" register has thirteen digit storage stages, two of which are disclosed in FIG. 52. Each stage has four bit sections, each of which is composed of the same type of input and memory flip-flops as that disclosed with respect to the "K" register. Each memory flip-flop also has a double-acting output relay 433, having its output channels 434 and 435 connected to the adder (FIG. 49B). The output signals of the relay 433 are always of opposite sign, as will be described more fully hereinafter.

Since, at this time, the amount in the "A" register is "0," the output relay 433 of each section of the first stage is in a negative condition, thus producing a negative pressure signal over the output channels 434 and a positive pressure signal over the output channel 435. Each of the output channels 434 and 435 is connected to one of the input relays 437a to 437d inclusive of the adder (FIG. 49B), one of which is located in each stage of the adder. The control port of each of the relays 437a to 437d inclusive is connected to the input channels 413a to 413d inclusive, over which the amount from the "K" register is transferred. It will be seen from FIG. 49B that the input channels 413a and 413b of the first and second bit sections are connected directly to the control port of the relays 437a and 437b, one of whose output channels 438 and 439 will represent the sum of the two signals located in its input channels, while the other channel will represent the complement of the sum. The use of a complement will be described hereinafter.

The output channels 438 and 439 of the first bit section are connected to a pair of relays 440a and 440b, which are part of a four-stacked relay, which, when in a positive condition, selects the "ones" complement of the digit being entered from the "K" register. As will be disclosed more fully hereinafter with relation to the sign logic section, the relays 440a to 440d inclusive are turned on when the signs of the amounts in the "A" register and

in the "K" register are different, thus indicating that a subtraction operation is to be performed.

The relays 441 and 442 in the third bit section of the stage and the relay 443 in the fourth bit section will automatically add the factor "six" to the digit being entered from the "K" register. Thus the sum of the "A" register and the "K" register with the "six" added thereto is transmitted to the upper input port of the control relays 444 to 447 inclusive, one of which is located in each bit section of the stage (FIG. 49B). The lower input port of the relays 444 to 447 inclusive will have a pressure signal representing the digit with a carry added thereto. Thus, if a positive pressure signal is applied to the control ports of the relays 444 to 447 inclusive, the lower input port is selected, and a signal representing the sum of the "K" register and the "A" register appears on the output channel of the relays. Associated with the relays 444 and 446 are second relays 444a and 446a, which function to amplify the carry signal transmitted from one bit section to the succeeding bit section.

Each bit section of the stage contains a pair of carry relays 448a, 448b to 451a, 451b inclusive. Each of these relays is a part of a double-stacked relay of the type shown in FIG. 7 but modified by the substitution of a second control pressure for the mid-pressure in channel 70 (FIG. 3). This pressure signal is opposite in sign to the other pressure signal applied in channel 69. Thus, in the first bit section, each of the control ports of the relays 448a and 448b is connected to the output channels 452, 453, respectively, of the relays 440b, 440a, each of which always has the opposite sign. One advantage of this type of construction is that each of the carry relays will switch at a faster rate, thus allowing the adder to operate at a relatively high rate of speed.

Another novel feature of this adder circuit is a carry skip arrangement for transferring a carry signal between stages of the adder and bit section of each stage. When each of the carry relays 448b, 451b is in a positive condition, the digit in the adder is equal to "fifteen." When this occurs, a positive pressure signal in the lower input port of the relay 451b is transmitted to the relays 448b to 451b inclusive over the output channels 454 of the relay 448b to the control port of the relay 455, thus orienting this relay positively to connect the output channel 456 of the relay to the lower input channel 457. If each of the stages is in the same condition, it will be seen that a carry signal generated in one of the stages of the adder or an end-around carry signal generated in the thirteenth digit section of the adder (FIG. 49A), and which is transmitted by the relay 458, is transferred to the relay 444 of the first bit section of each stage over channel 459, and also to each succeeding stage over channel 457, thus improving the speed of the operation of the adder when this condition occurs.

As part of the adder operation, the output signal of the first, second, and fourth bit sections is fed to a double-acting relay 460, as disclosed in the first bit section of the first stage. This switching of the relay 460 produces, in its output channels 461, 462, pressure signals representing the corresponding bit or the digit and its complement. The channels 461, 462 are connected to the relay 463a, which is controlled by a signal from the sign logic section (FIG. 49A) over channel 464 for selecting the complement signal when required. The operation of a sign logic section will be described hereinafter.

As disclosed above, the factor of "six" is added to each digit transferred from the "K" register. If, during the operation of the adder, a carry signal is produced, the digit representing the sum is left undisturbed. If a carry signal is not produced, the factor of "six" is automatically subtracted from the sum. This operation is controlled by the double-acting relay 465, located in the fourth bit section of each stage of the adder. The control port of this relay is connected to the output channel 466 of the carry

relay 451a of the fourth bit section of the stage. When a carry signal is produced by the relay 451a, a positive signal is in channel 466, thus turning on the relay 465. This switching of the relay produces a positive signal in its upper output channel 467, which is transmitted to the upper input port of the relay 455. If this relay is turned off at this time, the carry signal in its output channel 456 is transmitted to the next stage. The lower output channel 468 of the relay 465 transmits a negative pressure signal to the control port of the double-stacked double-acting relays 469a and 469b. These relays are associated with the relays 470a to 470d inclusive and will subtract the factor "six," when turned on, from the sum represented by the pressure signal appearing in the output channels of the relays 444 to 447 inclusive. At this time, these latter relays are turned off.

When no carry signal is produced in the stage, the relay 465 produces a positive pressure signal in the lower output channel 468, thus turning on the relays 469a and 469b. The relays 470a to 470d inclusive are turned on by the signal from the relay 446. Thus the sum that is produced as a result of an operation of the adder now has a "six" subtracted therefrom, the result appearing in binary digit decimal code, which, or its complement, will be transmitted over the output channels 471 to 474 inclusive of the stage to the "A" register to be entered therein upon the generation of a pair of clock signals in a manner to be described hereinafter.

Located on the left-hand side of FIG. 49A are a series of relays which constitute the sign logic section of the adder. The function of these relays is to determine whether the number in channels 413a to 413d inclusive (FIG. 49B) is to be added to or subtracted from the "A" register, and to generate the proper control signals to control the adder to function accordingly. Included is the relay 474, which, when turned on, provides a positive pressure signal over its output channel 475 to the control port of relays 440a to 440d inclusive of each stage except the thirteenth for switching each of the relays, resulting in the "nines" complement of the digit entered from the "K" register being taken. This digit will have had the factor of "six" added to it. Also included in this circuit is the relay 476, which transmits a positive pressure signal, when turned on, over the output channel 464 for the positive orientation of the relays 463a to 463c inclusive of each stage, resulting in the selection of the "nines" complement of the output digit of the stage.

Included in the sign logic section is a one-bit shift register, which stores the sign of the sum transmitted from the "A" register to the adder. This sign is generated by the relay 477a over its output channel 478 as a result of an operation of the adder. The shift register consists of an input flip-flop composed of the relays 479 and 480 and a memory flip-flop composed of the relays 481 and 477a. The channel 478 is connected to the "thirteen" bank of the "A" indicator 24 (FIG. 1) for positioning the indicator in the eighth position, where an appropriate figure will indicate a negative number. When the sign of the "A" register is negative, the channel 478 conducts a positive pressure signal.

The sign of the amount being transferred from the "K" register to the adder is generated as a result of control key operation. Referring to FIG. 47A, it is seen that the channels 353, 355, and 356, carrying the pressure signals representing the "Add" control key in the manner explained previously, will operate the relay 482, whose output channel 483 will have a negative pressure signal if the "Add" key is depressed. If the "Subtract" control key 93 (FIG. 15) had been depressed, a positive pressure signal would be transmitted over channel 483. The channel 483 is connected to the control port of the relay 562 (FIG. 49A) in the sign logic section.

The signs of the various control signals which are produced by the sign logic section and which affect the op-

eration of the adder are shown in tabular form in Table I below. The input signals A, K, and $\bar{K}$ refer to the sign of the digits of the "A" register in channel 478, the "K" or "M" register in channel 483, and the presence or absence of a carry output signal over channel 457 from the thirteenth stage of the adder. The output signals K₁, M, N, and S refer, respectively, to an end-around carry signal generated by the relay 458; the control signal for taking the "ones" complement of the input digit, generated by the relay 474; the control signal for taking the "nines" complement of the output digit, generated by the relay 476; and the sign of the output of the adder generated by the relay 477b. In the table, the "zero" represents the positive pressure signal, while a "one" represents a negative pressure signal.

TABLE I

A	B	$\bar{K}$	K	M	N	S
0	0	0	0	0	0	0
0	0	1	0	0	0	0
0	1	0	0	1	1	1
0	1	1	1	1	0	0
1	0	0	0	1	1	0
1	0	1	1	1	0	1
1	1	0	0	0	0	1
1	1	1	0	0	0	1

From the above table, it will be seen that, when the sign of the "K" register and the sign of the "A" register are opposite, the "ones" complement of the digit from the "K" register is taken and then is added to the amount in the "A" register. If no carry output signal is produced as a result of the adder operation, the "nines" complement of the sum is then taken. Thus, whether the operation of the adder is an addition or a subtraction, the operation is the same.

In the present example, with the sign of both the "A" and "K" registers being positive and with no carry output signal being generated over channel 457, the sum of the adding operation will be "seven," which will appear in the output channels 471 to 474 inclusive in the first stage. As disclosed previously, the binary signals generated by depression of the "Add" control key are connected to the control circuit shown in FIG. 46B, which generates signals for controlling the printing of the symbol representing the control key. These input signals over channels 353 to 356 inclusive result in a positive pressure signal derived from the input channel 355 being transmitted over channel 484 through relays 511a, 427b, and 485b to the upper input port of relay 486b. At this time, the relay 486b is turned off, thereby transmitting the positive pressure signal to the relay 487, turning this relay on. The lower input channel 488 of the relay 487 is connected to the output channel 489 of the relay 490, whose control port is connected to channel 285, over which appears the clock signal generated by the circuit in FIG. 39. It will be seen from this arrangement that, upon the generation of the first clock signal over channel 285, a positive pressure signal will be conducted through the relay 487 to the control port of the double-acting relay 491, which is turned on at this time, thereby resulting in the pressure signal in its output channels 492, 493 being switched. Thus the pressure signal in channel 492 is changed from negative to a positive condition, while the pressure signal in the channel 493 is changed from positive to negative. This switching of the relay 491 and the corresponding signals in the channels 492 and 493 are transmitted to each stage of the "A" register (FIG. 52), which function as clock signals to enter the sum, generated by the operation of the adder, in the "A" register. The output channels 492 and 493 of the relay 491 are also connected to the sign logic section (FIG. 49A), which results in the storing of the sign of the sum in the one-bit shift register.

As disclosed previously, each stage of the "A" register is composed of an input flip-flop and a memory flip-flop which consists of the relay 494 and the double-stacked double-acting relays 436 and 433. The storing of a digit in the relays 436a to 436d inclusive provides pressure signals in their upper output channels 415a to 415d inclusive representing the digit. These output channels are connected to the selector unit (FIG. 48) for transmission to the printer mechanism and also to the "A" indicator 24 (FIG. 1). Switching of the relay 436a to 436d inclusive by the clock signals in the channels 492, 493 results in the switching of the relay 433, whose output channels 434, 435 are connected to the adder in the manner described previously. Thus the digits stored in the memory relay of each stage of the "A" register are constantly being transmitted to the input of the adder, while the sum in the output channels of the adder is transmitted and stored in the input flip-flop of each stage of the "A" register. The switching of the clock signals in the channels 492, 493 results in the sum, in this case "seven," being transferred from the input flip-flops of each bit section of the first stage to the memory flip-flops in the manner explained previously with respect to the "K" register.

The switching of the clock signals over channels 492, 493 also transfers the sign of the sum from the input flip-flop of the one-bit register, disclosed in FIG. 49A, to the memory flip-flop in the same manner. Thus the output signal in channel 478 of the relay 477a is negative. The switching of the relay 477a also results in a negative signal being applied over the output channel 495 of the relay 477b. This channel is connected to the control port of the relay 496 (FIG. 47A), which is now off, thereby providing a negative pressure signal over its output channel to the control port of the relay 482. With the "Add" control key being depressed at this time, a negative signal is transmitted over the output channel 497 of the relay 617, through the relay 617a to the upper input port of the relay 482, which, at this time being in the negative condition, would transmit the negative pressure signal over the output channel 483. This signal represents the sign of the amount being transmitted to the adder from the "K" register. Since the sign of the sum of the adder has not changed, the negative signal from the relay 496 being transmitted over the output channel 483 does not change the sign. The channel 495 is also connected to the relay 638 (FIG. 45A), which is switched by a positive signal when the sign of the sum in the "A" register is negative. The channel 495 is also topped by the channel 495a, which is then connected to various relays of the Symbol Row Printer Logic circuit. When the "Total" key 90 (FIG. 15) is depressed, as will be described more fully hereinafter, the "A" register is printed. A symbol representing the sign of the sum in the "A" register is also printed as part of the same operation. At this time, the calculator is in condition for a new operation.

In the case of a subtraction operation, the functional operation of the various logic packages is the same as in the addition operation just disclosed. The only difference is that the pressure signals generated by the depression of the "Subtract" key 93 (FIG. 15) over channels 353, 355, and 356 (FIG. 47A) provide a positive pressure signal over the output channel 483, thereby indicating the negative sign of the amount being transferred to the adder from the "K" register in the manner described above. By referring to Table I, it will be seen that this positive pressure signal will affect the operation of the adder in the manner indicated. Thus the amount being transmitted from the "K" register is subtracted from the amount being transmitted to the adder from the "A" register. The control signals over the channels 353 to 356 inclusive also control the printer mechanism to print out a symbol which is representative of the use of the

"Subtract" key in the manner described previously with relation to the "Add" key.

Multiplication operation

In a multiplication operation, after the amount representing the multiplier has been entered into the amount keyboard, the "Enter Multiplier" key 87 (FIG. 15) is depressed. Actuation of this key operates the calculator to print the amount representing the multiplier in the "K" register in the manner described above and sets the "M" register (FIG. 52) equal to the "K" register in a manner to be described hereinafter. The multiplicand is then entered into the amount keyboard, followed by the depression of the "Multiply" key 89 (FIG. 15). This latter control key operates the calculator to perform the following operations: print the "K" register, add the product of the "K" register times the "M" register to the "A" register, set the "M" register equal to the "A" register, print the "A" register, and then reset the "A" register to zero. If at this time the "Negative Multiply" key 88 (FIG. 15) is depressed instead of the "Multiply" key 89, the operation would be the same except that the product of the "K" register times the "M" register would be subtracted from the "A" register.

To initiate a multiplication operation, the amount keys 62a (FIG. 15) in the amount section of the keyboard are depressed according to the digit or digits making up the multiplier. These digits are entered into the "K" register in the manner described previously. The "Enter Multiplier" key 87 is then depressed, which turns on the relay 502 (FIG. 36), thereby generating the binary-coded digit "one" over the output channels 325 to 328 inclusive. As disclosed previously, these fluid pressure signals are transmitted to the control keyboard circuit (FIG. 42A), where a positive pressure signal derived from the relay 333c is transmitted through the relays 340c, 498, 499, and 500, which, when turned on, provide a positive pressure signal through the relays 501c, 341 over the channel 342 through the relay 343 to turn on the relays 344, 346, and 332 (FIG. 42B), thereby initiating a clock signal (FIG. 39) in the manner described previously. The pressure signals over the channels 353 to 356 inclusive are also introduced into the printer control circuits shown in FIG. 43. These signals turn on the relay 397, so that, upon a clock signal being applied over the channel 285, an operation of the printer will result. The printer will print the multiplier, stored in the "K" register, and a symbol representing the control key 87.

With a positive pressure signal being applied over the channel 353 (FIG. 43) and a negative pressure signal being applied over the remaining input channels 354 to 356 inclusive, a positive pressure signal is transmitted through the relays 503, 490b, and 504a, which is turned off at this time, to the relay 505, which is turned on to provide a positive pressure signal over the channel 410, the channel being connected to the selector unit (FIG. 48), where the pressure signal switches the relays 407a to 407d inclusive of the first twelve stages and relays 408a to 408d inclusive of the thirteenth stage of the selector unit. The positive pressure signal transmitted through the relay 503 (FIG. 43) is also transmitted over the channel 506 through the relays 507 and 504b to the relay 508, which is turned on to supply a positive pressure signal over the channel 411, thereby turning on the relays 409a to 409d inclusive of the first twelve stages of the selector unit. Operation of these relays in the selector unit results in the digits stored in the "K" register being transmitted over the input channels 318a to 318d inclusive through the relays 409a to 409d inclusive to the "M" register (FIG. 50) over the lower output channels 414a to 414d inclusive. The switching of the relays 407a to 407d inclusive also connects the "K" register to the printer over the channels 412a to 412d inclusive in the manner described previously.

The "M" register, disclosed in FIG. 50, is similar in construction to the "K" register disclosed previously. The register consists of twelve digit storage stages, the first and last stages of which are shown in FIG. 50. The first stage is on the right side of the figure. Each bit section of each stage consists of an input flip-flop composed of the relays 509 and 510 and a memory flip-flop composed of the relays 511, 512a, and 512b. Each of the input channels 414a to 414d inclusive from the selector unit (FIG. 48) is connected to the lower input port of a storage relay 513a to 513d inclusive, located in each bit section. Upon the generation of a positive pressure signal over the control channel 514, the digit being transmitted over the input channels 414a to 414d inclusive is transferred from the storage relays 513a to 513d inclusive to the input flip-flops of each bit section.

A second storage relay 517a to 517d inclusive has its lower input port connected to the output channel of the relay 512b of the next stage on its right. Upon the generation of a positive control signal in the channel 291, the digit in each stage on the right is entered into the input flip-flop of the stage on the left through the relay 513. The digits are entered into the memory flip-flop of each bit section upon the subsequent generation of clock signals described hereinafter. The upper input channel of the relays 517a to 517d inclusive is connected to the output channel of the relays 512a to 512d inclusive of the previous stage. Whenever a digit is stored in this latter relay, the digit is automatically transferred to the input flip-flop of the next stage on the right, the digit being stored in that stage upon the generation of clock signals. This occurs when both relays 517 and 513 are turned off. Thus the effect of the clock signals is to shift the digits stored in each stage to the next stage on the right. At this time, a reset control signal for the first stage in channel 599 is positive, this signal being generated by the relay 600a and 600b (FIG. 42B).

Referring now to the control circuit in FIG. 46C, there is shown the relay 516, from which the control signal over the channel 514 is generated. This relay is controlled by the pressure signal over the input channels 353 to 356 inclusive. At this time, a positive pressure signal is in the channel 353, thereby turning on the relays 485a to 485d inclusive. This conditions the relay 485d to transmit a positive pressure signal generated from the relay 511b through the relays 518 and 427c to the relay 485d. This signal turns on the relay 519, which generates a positive signal over its output channel to the lower input port of the relays 486c and 486d, which in turn are controlled by the positive cycle clock signal generated over the channel 281 as a result of the first clock signal's being turned on in the control channel 285 of the relay 258 (FIG. 40C), described previously.

The switching of the relay 486d transmits the positive pressure signal in its lower input port to the relay 516, thereby switching the relay, resulting in the generation of a positive signal over the channel 514 to switch each of the relays 513a to 513d inclusive (FIG. 50) of each stage of the "M" register. Switching of these relays transmits pressure signals representing the digits in the input channels 412a to 412d inclusive to the input flip-flops of each bit section of the stage, as described above. When the second clock pulse is generated over the channel 285, the relay 490 (FIG. 46C) generates a positive pressure signal over the channels 489, 488 to the lower input port of the relay 520, which is turned on at this time. The positive signal transmitted through the relay 520 turns on the double-acting relay 521, whose output channels 522, 523 contain the clock signals for switching the "M" register. The switching of the relay 521 results in the switching of the signals in the output channels 522, 523, which shifts the digits stored in the input flip-flop of each bit section

of each stage of the "M" register into the memory flip-flop in the same manner as described previously in regard to the "K" and the "A" registers. Thus the output channels 524a to 524d inclusive of each stage of the "M" register at this time will contain the multiplier.

The multiplier is still stored in the "K" register. If the square of this number is desired at this time, all that is required is depression of the "Multiply" key. The digits stored in the "K" register representing the multiplier will now become the multiplicand. If the square of the multiplier is not desired, the amount keyboard 10 is used to enter the multiplicand into the "K" register in the manner described previously. The "Multiply" key 89 (FIG. 15) is then depressed. Referring to FIG. 53, 15 there is shown a flow diagram of the operation of the calculator when the "Multiply" key 89 or the "Negative Multiply" key 88 (FIG. 15) is depressed. The operation of the various logic circuits is the same in both cases, the only difference being that the sign of the amount being transferred from the "K" register to the adder unit is negative rather than positive when the "Negative Multiply" key is depressed, resulting in the product of the "K" register times the "M" register being subtracted from the "A" register, which in the case of the "Multiply" key is added to the "A" register.

The depression of the "Multiply" key 89 results in the binary digit "seven" being transmitted over the output channels 325 to 328 inclusive (FIG. 36). At this time, there are two interlocks present, which, if actuated, prevent any further operation of the calculator. The first interlock prevents operation of the calculator when no number is stored in the "K" register. This interlock eliminates the multiplication of the multiplier by a zero. Referring to FIGS. 40A and 40B, there is shown, 20 located below the shift counter of the "K" register, a buffer circuit consisting of four flip-flops, each flip-flop composed of the relays 515 and 526 and representing the bit section of a digit. Each of the flip-flops is connected to one of the double-acting relays 276 to 279 inclusive located in the "K" register shift counter. Any digit stored in the relays 276 to 279 inclusive is transferred to the flip-flops of the buffer circuit. Thus the buffer circuit contains a number representing the number of digits that have been entered into the "K" register. If at this time a zero is stored in the buffer circuit, the upper output channel 525 of each double-acting relay 526 contains a positive pressure control signal, represented in FIG. 53 as K_0 . This signal is transmitted to the control port of the relay 499 (FIG. 42A), 25 which is turned on to prevent the generation of a positive control signal from the relay 500 being transmitted to the cycle clock circuit (FIG. 42B), thus disabling the generation of the control signal K_L (FIG. 53) in channel 280 and the operation of the clock circuit (FIG. 39).

The second interlock prevents the product of the multiplier stored in the "M" register and the multiplicand in the "K" register from exceeding the capacity of the "A" register. In the multiplication of two numbers, the digits in the product never exceed the total number of digits in the multiplicand and the multiplier. Since the capacity of both the "M" register and the "K" register is each twelve digits, or a total of twenty-four digits, and the "A" register has a total capacity of thirteen digits, the calculator will be disabled from further operation when the product exceeds twelve digits.

Referring to the "M" register (FIG. 50), it will be seen that the double-acting relays 510, 527, 528, and 529 of each bit section are interconnected and that, if a zero is stored in these stages, the upper output channel 529 of the relay 528 will be conducting a positive pressure signal derived from the relay 510. If any of the relays 510, 526, 527, or 528 is turned on, a negative pressure signal appears in the output channel 529. Each of the output channels 529 of the first eleven stages of the "M" register is shown 70 connected to the control port of the multiple-stacked re-

lays 530 (FIGS. 40B and 40C). The output channel 529 of the twelfth stage is shown connected to the relay 531 (FIG. 40C), while the eleventh stage is shown connected to the output relay 530a to 530d inclusive (FIG. 40B) of the circuit. The function of this circuit is to generate in the output channels 532 to 535 inclusive of the relays 530a to 530d inclusive a digit representing the number of digits stored in the "M" register.

Each of the output channels 532 to 535 inclusive is connected to the upper input port of a series of relays 536a to 536d inclusive (FIG. 40B). The relay 536 is part of a flip-flop which includes the double-acting relay 537. As disclosed previously, the buffer circuit (FIG. 40A) stores the number of digits plus the factor of "three" that is in the "K" register which appears in the output channels of the relays 276 to 279 inclusive of the shift counter. This digit is transferred from the lower input port of the relay 526 of each bit section over the channels 538 to 541 inclusive to the upper input port of the relays 542a to 542d inclusive. If the sum of the two digits is greater than "fifteen," a positive pressure signal appears in the output channel 543 of the output relay 544, which signal turns on the relay 545. This results in the relay 545 transmitting a positive pressure signal over its output channel 546, this signal being characterized as M_{of} in FIG. 53. The output channel 546 is connected to the control port of the relay 498 (FIG. 42A), which, when turned on, inhibits the turning on of the relay 332 (FIG. 42B) and the cycle clock circuit, thus preventing the operation of the clock circuit (FIG. 39). It should be noted that the effect of this interlock is similar to the effect of the first interlock. The first interlock functions in both a multiplication and a division operation, while the second interlock functions only during a multiplication operation. Both interlocks occur before the "Multiply" key has been depressed.

If both interlocks are not turned on at this time, the signals generated by depression of the "Multiply" key 89 generate control signals in the manner described previously in relation to the "Add" and the "Enter Multiplier" control keys. Thus the cycle clock circuit (FIG. 42B) is turned on, with a positive pressure signal being transmitted over the output channel 280 of the relay 332 to turn on the clock circuit (FIG. 39). This signal is characterized as K_L in FIG. 53, the clock circuit being represented by the letter "C." This positive pressure signal over the channel 280 locks the buffer circuit of the shift counter in FIG. 40A, thus storing the number of digits contained in the "K" register plus the factor of "three." The initiation of a printing operation (FIG. 43) will occur for the printing of the "K" register. The control signals in the channels 353 to 356 inclusive generate a positive pressure signal in the output channel 547 (FIG. 44) of the relay 548 and a positive pressure signal in the output channel 363 of the relay 362. These control signals will initiate or condition various circuits for operation, as will be described more fully hereinafter.

The switching of the pressure signals in the output channel 331 of the relay 349 (FIG. 42B) and in the channel 264 (FIG. 40C) from positive to negative, together with the changing of the pressure and the control signal in the channel 273 (FIG. 46C) from a negative condition to a positive condition, will reset the "K" register shift counter (FIG. 40A) to zero. The switching of the pressure signal in channel 547 (FIG. 40C) will switch the relays 542a to 542d inclusive in the carry generating circuit (FIGS. 40B and 40C), so that the output of the shift counter (FIG. 40A), which is normally equal to the digit stored in the relays 276 to 279 inclusive of the shift counter plus the factor of "one," is subtracted from the digit representing the number of digits stored in the "M" register, this latter digit now being stored in the relays 537a to 537d inclusive (FIG. 40B).

The storing of the "M" register digit in the relays 537a to 537d inclusive of the carry generator circuit occurred

when the control signal in channel 280 (FIGS. 40A and 40B) was switched from a negative pressure signal to a positive pressure signal.

As will be described more fully hereinafter, each time the "K" register is shifted to the left during a multiplication operation, the shift counter is up-counted by "one" until the digit in the shift counter is equal to the digit stored in the relays 537a to 537d inclusive. When this occurs, a positive pressure signal is generated over channel 546 (M_{of}), which prevents the "K" register from further shifting, thus ending the multiplication process.

Referring to FIGS. 41A and 41B, there is shown the Sequence Counter circuit, which generates a series of control signals during a multiplication or division operation of the calculator. These signals are used to operate various logic circuits by controlling the signals which control the circuits themselves. As shown, the Sequence Counter circuit is divided into four sections, each section generating at least two control signals. The upper section, located in FIG. 41B, generates three control signals. Each section comprises a main circuit for generating the main signal and a one clock delay circuit for generating the second control signal. Each of the main control signals over channels 549 to 552 inclusive are derived from the output relay of the main circuit, while the secondary control signals over channels 549a to 552a inclusive are derived from the output relay of the delay circuit. Thus the signals generated over channels 549a to 552a inclusive will occur one clock cycle later than the signals over channels 549 to 552 inclusive. The two signals generated from each section are always of the same sign. A third control signal is generated in channel 549b and is always of the opposite sign to that signal in channel 549.

Reference should be made to the following Table II, which shows the values of the various control signals in the output channels 549 to 552 inclusive of the Sequence Counter at certain time intervals.

TABLE II

Time T	Channel			
	549	550	551	552
0-----	0	0	0	0
1-----	0	0	0	1
2-----	0	0	1	0
3-----	0	0	1	0
4-----	0	1	1	0
5-----	0	1	1	1
6-----	0	1	0	1
7-----	0	1	0	0
10-----	1	0	0	0
11-----	1	0	0	1
12-----	1	0	1	1
13-----	1	0	1	0
14-----	1	1	1	0
15-----	1	1	1	1
16-----	1	1	1	1

These time intervals are indicated in FIGS. 53 and 54 and are used at that time to control the operation of the various circuits in the manner indicated. Each time interval represents the generation of a clock signal. At the time of the resetting of the shift counter (FIG. 40A) to a zero condition, a positive control signal is generated over the output channel 553 (FIG. 46B) of the relay 554. The Sequence Counter is now in a T_0 condition. This signal is the result of a control signal being transmitted over channel 549b (FIGS. 41B and 46A), and 547 (FIGS. 43 and 46A), and channels 552a (FIGS. 41A and 46B), which control the various relays to produce the signal generated by the relay 554. This positive signal is transmitted to the control port of the relay 555 (FIG. 47B), which is turned on to produce a positive signal in its output channel 556. The signal is transmitted to the control port of the four-stacked relay 557a to 557d inclusive. The effect of the switching of these relays is to transfer a digit from a loading circuit (FIG. 47A) to the Multiplication-Division (M/D) counter (FIGS. 47B and

47C) input flip-flops, where the digit is up-counted by "one" in the case of a division operation or down-counted by "one" in the case of a multiplication operation.

As is well known, in the art, the multiplication operation performed by the calculator consists of adding the multiplicand, stored in the "K" register, to the "A" register according to the digit or digits which constitute the multiplier, stored in the "M" register. This is accomplished by storing each digit of the multiplier in the M/D counter and operating the adder to add the "K" register to the "A" register, each time down-counting the multiplier digit by "one." As each digit of the multiplier is reduced to zero, the "M" register is shifted right to load the next multiplier digit into the M/D counter. Each time the "M" register shifted right, the "K" register is shifted left, thereby allowing the least significant digit of the "K" register to be added to the proper stage of the "A" register. This also adds "one" to the shift counter (FIG. 40A). As disclosed above, the digit stored in the shift counter is subtracted from the digit representing the "M" register in the carry generating account (FIGS. 40B and 40C). This operation is repeated until the control signal in channel 546 (M_{0f}) becomes positive, indicating that the last digit of the multiplier has been entered into the M/D counter. The next operation is to return the digits in the "K" and "M" registers to their home position.

The digit that is transferred into the loading circuit of the M/D counter at this time is taken from the first stage of the "M" register. This is indicated in FIG. 47A by the relays 512a, 512c, 512e, and 512g, which are part of the memory flip-flop of each bit section. The digit is transferred to the loading circuit over the output channels 524a to 524d inclusive. The dotted lines 558 indicate that the relays 512a, 512c, 512e, and 512g are located in the first stage of the "M" register (FIG. 50). The next dotted line 559 indicates part of the circuit that is contained in the selector unit (FIG. 48). Here the digit from the first stage of the "M" register is transferred over the channels 416a to 416d inclusive to the selector unit.

The loading circuit located in the upper portion of FIG. 47A to which the digit in the first stage of the "M" register is transferred provides a multiplication short-cut in that, if the multiplier digit is "four" or less, the number is transferred to the relays 557a to 557d inclusive. See FIG. 47B. If the multiplier digit is "five" or more, the "tens" complement of the digit is taken and transferred to the relays 557a to 557d inclusive, and the factor of "1" is added to the next multiplier digit when it is loaded from the "M" register. As part of this latter operation, a positive signal is generated, when a "one" is to be added to the multiplier digit, over the output channel 560 (FIG. 47A) of the relay 561, which is part of a memory flip-flop composed of the relays 561 and 563. This signal is transferred from a delay circuit composed of a pair of flip-flops containing the relays 641 and 642, respectively. The pressure signals in the channel 560 are transmitted to the Sequence Counter (FIG. 41B) for adjusting the output control signals of the counter during the next clock pulse operation.

The digits from the first stage of the "M" register are transferred to a series of storage relays 564 to 567 inclusive (FIG. 47B) from the loading circuit upon the switching of the relays 557a to 557d inclusive by the positive pressure signal in channel 556, in combination with the generation of a clock pulse over channel 568 (FIG. 47C). This clock signal switches a series of flip-flops (FIG. 47B) to represent the digit transferred from the relays 557a to 557d inclusive. The clock signal is generated from the relay 569 (FIG. 45B). The digit stored in the relays 564 to 567 inclusive is introduced into a counter circuit which is controlled by the relays 570a to 570c inclusive. When these relays are turned off, the circuit subtracts "one" from the digit entered, while, if turned on, the circuit adds "one" to the digit. The output of the counter circuit is connected to the upper input

ports of the relays 557a to 557d inclusive (FIG. 47B). Thus the new digit is transferred to the storage relays 564 to 567 inclusive upon the generation of a new clock signal over channel 568.

Referring again to FIG. 53, it will be seen from the flow diagram that, after the printing of the "K" register, the resetting of the shift counter to zero and the loading of the M/D counter with the digit from the first stage of the "M" register, the Sequence Counter (FIGS. 41A and 41B) is adjusted to produce control signals according to T₁, as set out in Table II. At this time, the calculator will check the sign of the control signals M_{0f} and L. The flow diagram (FIG. 53) is so illustrated that those control signals located within a diamond block are checked by the calculator to see whether they are true (1) or false (0). The condition of the signals controls the operation of the calculator, as shown in the diagram. If, at this time, the M_{0f} signal in channel 546 (FIG. 40C) is off, while the L signal in channel 560 (FIG. 47A) is off, this indicates that the last multiplier digit loaded in the M/D counter was a "four" or less. If the digit was a "five" or greater, thus making L positive and the condition of the signals M_{0f} and L false (0), the "M" register would be required to be shifted to the right, so that "one" may be added to the next multiplier digit. Assuming at this time that this is the case, even though normally this would not be true, the next signal that is checked by the calculator is the signal generated by the relay 571 (FIG. 47C) over its output channel 572, this signal being characterized as the digit counter haut, or D.H. This signal is positive when the M/D counter reaches "nine" on addition or "zero" on subtraction. If the D.H. signal is positive, the "M" register is shifted to the right, so that the next multiplier digit may be loaded into the M/D counter. This is accomplished by the D.H. positive signal in channel 572 being transmitted to the control port of relay 573 (FIG. 46A), which produces a negative pressure signal over its output channel 574. This signal, together with the control signals from the Sequence Counter, results in the switching of the relay 521 (FIG. 46C), thereby switching the clock signal in the output channels 522 and 523. These signals, as previously described, shift each of the stages of the "M" register to the right. The D.H. positive signal also adjusts the Sequence Counter over channel 572 (FIG. 41B) to generate control signals indicated as T₂ in Table II. These control signals switch the relay 270 (FIG. 46C) and the clock signals in channels 271 and 272, thus shifting the "K" register to the left, and also generate a positive signal over channel 273 (FIG. 46C) from relay 268b. This signal adds "one" to the shift counter (FIG. 40A). In addition, the next multiplier digit from the "M" register is loaded into the M/D counter. At this time, the Sequence Counter goes back to T₁, and the operation of the calculator, as indicated in FIG. 53, is repeated.

If the M/D counter has not reached zero, which in the present example is the case, the D.H. signal is negative. With the Sequence Counter being at T₁, the relay 491 (FIG. 46C) is switched, resulting in the digit representing the multiplicand stored in the "K" register being added into the "A" register. Also, the relay 521 (FIG. 46C) is switched, thereby shifting the "M" register to the right. As part of this same operation, the clock signal generated over channel 568 (FIG. 47C) switches the flip-flops of the digit counter (FIG. 47B), thereby transferring a digit representing the last digit stored in the relays 564 to 567 inclusive, but down-counted by "one," to the relays 557a to 557d inclusive. At the end of this operation, the Sequence Counter is adjusted to provide the control signals indicated as T₃ in Table II. If at this time the D.H. signal in channel 572 (FIG. 47C) is negative, the "K" register is again added to the "A" register, and the M/D counter operates to down-count the digits stored in the counter by "one." It is seen from FIG. 53 that this operation will continue until the M/D counter

operation results in the entry of a "zero" into the digit counter. At this time, the D.H. signal over channel 572 becomes positive, resulting in the "K" register's being shifted to the left, the addition of "one" to the shift counter (FIG. 40A), and the loading of the M/D counter with the digits now stored in the first stage of the "M" register. The Sequence Counter goes back to T_1 , and the operation is repeated. It may be seen from this arrangement that the multiplicand stored in the "K" register is added to the "A" register at a frequency that equals the number representing the multiplier.

As disclosed above, each time the "M" register is shifted to the right, a "one" is added to the shift counter (FIG. 40A), this operation continuing until the output of the carry circuit (FIG. 40B) becomes "zero," thus indicating that the number of "M" register shift operations equals the number of digits in the "M" register. This condition is signalled by the conduction of a positive pressure signal M_{0f} (FIG. 53) over channel 546 (FIG. 40C). As shown in FIG. 53, if at this time the last multiplier digit transferred from the "M" register was a "four" or less, a negative pressure signal is generated over channel 560 (FIG. 47A), which is transferred to the Sequence Counter (FIG. 41B), adjusting its control signals so that a positive signal is generated over the output channel 291 (FIG. 42B) of the relays 581 and 582 one clock cycle later. These signals shift the "M" register to the left and the "K" register to the right in conjunction with the generation of their clock signals, as disclosed below. The control signal in channel 291 is also connected to the control port of the relay 290a to 290d inclusive (FIG. 40A), which conditions the shift counter to be down-counted by "one" each time the clock signal over channel 273 is turned on. At this time, the Sequence Counter is adjusted to a T_4 condition.

If the K.B.O.F. (FIG. 53) control signal in channel 286a (FIG. 40A) is not positive at this time, indicating that the shift counter is not at zero when in a down-counting condition, the control signals generated by the Sequence Counter will switch the relays 270 and 521 (FIG. 46C), resulting in the shifting of the "K" register to the right towards its home position and the "M" register to the left, due to the generation of a positive control signal in channel 291 (FIG. 42B). A positive signal is also generated at this time over channel 273 (FIG. 46C), which is a clock signal for the shift counter, the counter being down-counted by "one" as described above. This operation is repeated until the shift counter is at zero, indicating that the "K" register has been shifted to its home position. When the shift counter is at zero, the K.B.O.F. control signal is turned on.

If, at this time, neither the "Mode" key 84 (FIG. 15) nor the "%" key 81 in combination with the "Multiply" key 89 has been depressed, the control signals from the Sequence Counter generate positive pressure signals over the output channels 575 and 576 (FIG. 45A) of relays 577 and 578 (FIG. 45B), respectively. The positive signal in the channel 575 is transmitted to the upper input port of the relay 399 (FIG. 43), which transmits the signal to turn on the relay 397. Upon the generation of the clock signal over channel 285, the printer switch 404 is actuated to initiate a printing operation to print out the product of the multiplication operation now stored in the "A" register in a manner to be described.

The positive pressure signal in channel 576 (FIG. 45A) is transmitted to the lower input port of the relay 504a (FIG. 43), which at this time is turned on by the control signal generated over channel 363 (FIG. 44) as a result of the "Multiply" key's being depressed. This positive signal turns on the relay 505, thus generating a positive control signal over the output channel 410, which, as disclosed previously, turns on the relays 407 and 408 of the selector unit (FIG. 48). The turning on of these relays connects the output of the "A" register to the printer over channels 412a to 412d inclusive for the print-

ing of the product, now stored therein. At this time, the output channels of the "A" register are also connected to the "M" register. The relay 521 (FIG. 46C) is switched at this time to enter the product of the multiplication operation into the "M" register from the "A" register. The Sequence Counter is now adjusted to the T_6 condition of Table II.

With the generation of a new control signal from the Sequence Counter, the relay 579 (FIG. 46C) in the control circuit is turned on, thus switching the signal in the output channel 580 from positive to a negative pressure signal. The channel 580 is connected to the lower input port of the relay 492 (FIG. 52) of each bit section in each stage of the "A" register. When the next clock signal is generated over channel 285 (FIG. 46C) from FIG. 39, the relay 491 is switched in the manner described previously, resulting in the "A" register clock signals in channels 492 and 493 being switched. These signals, together with the signal in channel 580, reset the "A" register to a zero condition.

The generation of a clock signal at this time over channel 285 also reloads the shift counter (FIG. 40A) with the digits stored in the buffer circuit, and switches the control signal (K_L) in channel 280 (FIG. 42B), which turns off the clock circuit (FIG. 39) and turns off the control signals in channel 291 (FIG. 42B). Referring to FIG. 40A, it was disclosed previously that, upon the generation of a positive pressure control signal (K_L) in channel 280, the digit representing the number of digits plus the factor "3" that was stored in the "K" register was also stored in the buffer circuit located below the shift counter. It is seen that the output channels 538 to 541 inclusive of the buffer circuit are each connected to the lower input ports of the relays 284a to 284d inclusive. When the shift counter was down-counted to zero during the restoration of the "K" register to its home position, described above, the signal in channel 286 (K.B.O.F.) became positive, thereby turning on the relays 538 to 541 inclusive. When the next clock pulse over channel 273 (FIGS. 46C and 40A) is generated, the digits stored in the buffer circuit are entered into the storage relays 276 to 279 inclusive in the manner described previously.

The control signals generated by the sequence counter at this time will switch the relays 581 and 582 (FIG. 42B) at the arrival of the next clock signal over channel 285. The control signals from the Sequence Counter also generate a positive control signal over the output channel 583 (FIG. 46A) of the relay 584. This channel is connected to the lower input port of relay 364 (FIG. 42B), which transmits this signal to condition the delay circuit, so that, upon the generation of a clock signal over channel 285, relay 332 is switched to turn off the control signal (K_L) in channel 280. As previously described, this switching of the signal in channel 280 turns off the clock circuit in FIG. 39. The Sequence Counter at this time returns to its original condition, and the multiplication operation of the calculator is terminated.

If the "Mode" key 584 (FIG. 15) had been depressed in conjunction with the "Multiply" key 89, a positive control signal would have been generated over channel 403 (FIG. 36). This channel is connected to one of a series of memory flip-flop circuits (FIG. 42A), which is switched so that the output channel 586 of the relay 587 conducts a positive pressure signal whenever the "Mode" key 84 is depressed. These memory flip-flops provide a signal indicating that a particular non-motorized key has been depressed even though the key has been returned to home position. When a control signal operates the delay circuit (FIG. 42B) to turn off the control signal (K_L) in channel 280 to end the machine operation, a positive signal in the output channel of relay 396d (FIG. 42B) is transmitted over channel 588 to the relays 589a to 589d inclusive (FIG. 42A) of each memory flip-flop, thereby turning off each of the memory flip-flops.

The signal in channel 586 generated by depression of

the "Mode" key 84 is transmitted to the Sequence Counter (FIG. 41B) and also to the control keyboard register (FIG. 43), the latter signal initiating an operation of the printer, resulting in the printing of the product now stored in the "A" register in the manner described above. The Sequence Counter then adjusts to the T_7 condition, resulting in the return of the various circuits to their home position, as described previously.

If, at the time the Sequence Counter was at T_4 and the control signal (K.B.Q.F.) in channel 286a (FIG. 40A) was positive, the depression of the "Multiply" key 89 and the "%" key 81 would result in the rounding off of the product by two digits. The depression of the "%" key produces a positive pressure signal over the channel 590 (FIG. 36), which is transmitted to the memory flip-flop (FIG. 42A), where a positive signal is transmitted over channel 591 from the relay 592. This signal is transmitted to the Sequence Counter (FIG. 41B), which, together with the positive pressure signal over channel 286, generates a control signal resulting in the following operation: A positive signal is generated over channel 593 from relay 594 (FIG. 42B), and the relay 521 (FIG. 46C), the relay 581 (FIG. 42B), and the relay 582 are turned on. The positive pressure signal over channel 593 is transmitted to the upper input port of the relay 595, which is turned off at this time. This signal is then transmitted to relay 596, thereby switching the signal in the output channel 597 of the relay from a positive condition to a negative condition. The signal in channel 597 is a reset signal for the "M" register (FIG. 50) and resets the last eleven stages of the register. A positive signal in the output channel 599 (FIG. 42B) of the double-stacked relay 600a, 600b provides a reset control signal to the first stage of the "M" register. The positive control signal in channel 593 is also transmitted to the control port of a four-stacked relay 601a to 601b inclusive (FIG. 47C), the relays being turned on to generate the digit "5" over their output channels 602, 603, 604, and 605. This digit "5" is transmitted through the relays 606a to 606d inclusive, 607 to 610 inclusive, over the output channel 611 to 614 inclusive to the first stage of the "M" register. When the clock signals of the "M" register are switched in channels 522, 523 (FIG. 46C), the last eleven stages are reset to zero, and the digit "5" is entered into the first stage of the "M" register. The Sequence Counter then assumes the T_{10} condition of Table II. The next six adjustments of the Sequence Counter T_{11} to T_{16} inclusive are controlled by each succeeding clock signal over channel 285 (FIG. 41B).

At T_{10} , the Sequence Counter generates control signals, resulting in the transmission of a positive pressure signal over the output channels 291 of the relays 581 (FIG. 42B) and 582. One of these signals is transmitted to the "M" register, resulting in the digit "5" being shifted from the first stage of the register to the second stage upon the switching of the clock signals in channels 522 and 523 (FIGS. 46C and 50). At T_{11} , a positive signal is generated in the output channel 611 (FIG. 46B) of the relay 612. This signal is transmitted to the lower input port of the relay 504b (FIG. 43), which transmits the signal to the control port of the relay 508. The relay 508 generates a positive pressure signal over the output channel 411, which turns on the relays 409a to 409d inclusive (FIG. 48) in the selector unit circuit. This switching of the relays connects the output channels 416a to 416d inclusive of the "M" register to the input channels 413a to 413d inclusive of the adder (FIG. 49), thereby adding the digits in the "M" register to the "A" register. This sum is entered into the "A" register upon the subsequent switching of the clock signals in channels 492 and 493 (FIGS. 46C and 52) in the manner described previously.

At T_{12} , control signals of the Sequence Counter will turn off the relays 581 and 582 (FIG. 42B) and generate a positive pressure signal to channel 576 (FIGS. 45A and 43), which, as previously described, will, in the selector

5 circuit, (FIG. 48) connect the "A" register to the "M" register, so that the sum in the "A" register will be transferred to the "M" register upon the switching of the relay 521 (FIG. 46C). At T_{13} and T_{14} , the relay 521 (FIG. 46C) is switched for shifting the digits in the "M" register to their home position. At T_{15} , a positive pressure signal is generated over the output channels 575 of the relay 577 (FIG. 45A), which operates the printer switch 404 (FIG. 43) in the manner described previously. A positive pressure signal is also generated over channel 576 (FIGS. 45A and 44), which, as described above, controls the selector circuit (FIG. 48), so that the output channels 416a to 416d inclusive are connected to the input channels 412a to 412d inclusive of the printer, whereby the amount stored in the "M" register is printed. This amount is the result of rounding off the product of the multiplication. It is seen from this operation that the digit "50" was added to the last two least significant digits of the product. These last two digits were then dropped. 10 Thus, if the last two digits of the product were greater than "50," the third last digit was increased by "1." If not, the third last digit remains the same.

15 At this time, the Sequence Counter is at T_{16} , which, as may be seen from FIG. 53, results in the return of the various circuits to their home position, as described previously. A division operation of the calculator will now be described.

Division operation

20 At the beginning of this operation, an amount representing the dividend is entered into the keyboard and is transferred to the "K" register in the manner described previously. The "Enter Dividend" key 85 (FIGS. 15 and 36) is then depressed, which results in the relays 612a and 612b (FIG. 36) being switched on to provide positive pressure signals over the output channels 327 and 328 of the keyboard. In the same manner as described previously with regard to a multiplication operation, these control signals will print the dividend that is being stored in the "K" register, reset the "A" register, and then set the "A" register equal to the "K" register. The amount representing the divisor is then entered into the keyboard, followed by depression of the "Divide" key 86 (FIG. 15). The flow diagram of the operation of the calculator upon depression of the "Divide" key is disclosed in FIG. 54. 25 This operation includes the printing of the "K" register, the resetting of the "M" register, the dividing of the "A" register by the "K" register, followed by the transfer of the quotient into the "M" register and leaving the remainder in the "A" register, the printing of the "M" register, and finally the printing of the "A" register.

30 The operation of the Sequence Counter is the same as that in the multiplication operation, with the value set out in Table II being applicable in this operation. Upon depression of the "Divide" key 86 (FIG. 36), the binary digit "3" is generated over the output channels 325 to 328 inclusive, which signals are transferred to FIG. 42A, where the digits are stored in the memory flip-flops in the manner disclosed previously. These control signals will turn on the control signal (K_L) in channel 280 (FIG. 42B) of the relay 332, which operates the clock circuit (FIG. 39). Control signals over the output channels 353 to 356 inclusive (FIG. 42A) will turn on relays 361a and 361b (FIG. 44), thereby generating a positive control signal over the output channel 613. A positive signal is also generated over the output channel 363 of the relay 362. 35

40 The positive control signals in channel 613 are transmitted to the Sequence Counter (FIG. 41B) for conditioning the control circuits of the counter; to the control port of the relays 614a and 614b (FIG. 42B) to condition control circuits for switching the control signal in channel 599, thereby resetting the "M" register and turning on the control relays 581 and 582; to the symbol row logic circuits (FIG. 45B) for the printing of the symbols associated with a division operation; to the control port 45 of the relays 615a to 615d inclusive (FIG. 46A), which

condition various control signals for operation; and to the control port of the relays 606a to 606d inclusive (FIG. 47C), which turns off the relays 601a to 601d inclusive from the first stage of the "M" register and connects the output channels (618 to 621) of the counter circuit (FIG. 47C) to the first stage of the "M" register.

As shown in FIG. 54, the first interlock, described previously in connection with a multiplication operation, is also present in a division operation. This interlock prevents operation of the calculator if no number is stored in the "K" register, which in effect prevents the division of a number by zero. If the output signal in channel 525 (K_0) (FIG. 40A) of the "K" register buffer circuit is negative, the relay 499 (FIG. 42A) will remain in a negative condition, thus allowing, when the "Divide" key is depressed, the positive pressure signal (K_L) to be generated in channel 280 (FIG. 42B) of the relay 332 to turn on the clock circuit (FIG. 39), the clock signal (C) being transmitted over the channel 285. With the Sequence Counter at T_0 , the first clock signal in channel 285 operates the following circuits: a positive pressure signal will control the relay 397 (FIG. 43) to operate the printer switch 404 (FIG. 43), thereby initiating the printing of the divisor stored in the "K" register; the "K" register shift counter (FIG. 40A) will be reset to zero by the switching of the pressure signals in channel 264 of relay 257A (FIG. 40C), together with the generation of a positive pressure signal in channel 331 (FIG. 40B) in the same manner described previously with respect to FIG. 53; the memory relays 564 to 567 inclusive (FIG. 47B) of the M/D counter circuit will be reset to zero by the control signal in channels 280 and 281 (FIG. 47B), which switches the relays 615a to 615d inclusive to provide a zero in their output channels, the digit being transferred to the input flip-flops of the relays 564 to 567 inclusive, to be entered into these relays upon the generation of the clock signal over the channel 568 (FIGS. 47B and 47C); and the generation of a positive control signal over the output channel 616 of the relay 614a (FIG. 42B), resulting in the switching of the signal in channels 599 and 597, thereby resetting the "M" register upon the switching of the relay 521 (FIG. 46C) in the manner described previously.

At this time, the Sequence Counter (FIGS. 41A and 41B) provides control signals according to T_1 of Table II. The division operation consists of repeatedly subtracting the divisor that is stored in the "K" register from the dividend, which is stored in the "A" register. This operation is repeated until an overdraft occurs, indicating that, in the last subtraction operation, the digit of the divisor was shifted past the last digit of the dividend. As was disclosed previously in the description of the adder (FIG. 49), a positive pressure signal is generated in channel 464 (FIG. 49A) when such an overdraft occurs. This signal is represented as "N" in the flow diagram (FIG. 54). At this time, the digits representing the divisor in the "K" register is shifted so as to be in alignment with the digits representing the dividend stored in the "A" register. This occurs when the Sequence Counter is at T_1 . The two control signals used to check this operation are the "N" signal and the control signal in channel 546 ($M_{O.F.}$) of relay 545 (FIG. 40C), which, as previously disclosed, limits the digits that may be entered into the "A" register from the "M" and "K" registers to twelve.

Normally, both the "N" and the " $M_{O.F.}$ " signals are negative. The control signals of the Sequence Counter generate a positive signal over the output channel 269 of relay 268a (FIG. 46C), which turns on the relay 270, thereby shifting the digits in the "K" register one stage to the left. Also, a clock control signal is generated over channel 273, which adds "1" to the shift counter (FIG. 40A). Since the output of the "K" register is connected to the adder, this shifting of the "K" register continues

until an overdraft occurs, represented by the positive signal "N" in channel 464 (FIG. 49A). This signal indicates that the "K" register has been overshifted by one stage. The positive signal in channel 464 controls the Sequence Counter to generate positive control signals over channel 291 (FIG. 42B). If at this time the control signal ($K_{B.O.F.}$) in channel 286a (FIG. 40B) is negative, the control signal in channel 291 (FIG. 51) shifts the "K" register back one stage while switching the relays 290a to 290d inclusive (FIG. 40A) to down-count the shift counter by "one." The Sequence Counter is then adjusted to operate at T_3 .

If, in the above example, the shifting of the "K" register to the left in the aligning of the divisor with the dividend resulted in the shifting of the highest significant digit into the twelfth stage of the "K" register, the control signal ($M_{O.F.}$) in channel 546 (FIG. 40C) will be turned on in the following manner. At the time the divisor was entered into the "K" register, this number, with the factor of "3" added thereto, was accumulated in the shift counter (FIG. 40A) and the buffer circuit in the manner described previously. Upon the turning on of the control signal (K_L) in channel 280 (FIG. 42B) as the result of the depression of the "Divide" key, the divisor was transferred from the buffer circuit into the carry-generating circuit (FIGS. 40B and 40C). As the "K" register is shifted left, the number of shifts is added to the carry circuit from the shift counter until the carry circuit generates the number "fifteen," at which time the control signal (K_R) in channel 291 (FIG. 42B) and to signal conditions the Sequence Counter to turn on the control signal (K_R) in channel 291 (FIG. 42B) and to generate control signals according to T_3 of Table II.

At T_3 , the Sequence Counter checks the condition of the control signal (D.H.) in the output channel 572 of the relay 571 (FIG. 47C). This signal is turned on when a positive control signal (N) is transmitted over channel 464 (FIGS. 49A and 47C), thereby indicating an overdraft condition of the adder. Normally, at this time, this control signal is negative. There will now begin the actual division operation, as described previously, by subtracting the divisor in the "K" register from the dividend stored in the "A" register. The control of the subtraction operation of the adder (FIG. 9) is, as disclosed previously, by a negative pressure signal's being transmitted over channel 483 (FIGS. 47A and 49A). This signal was generated by the control signals in channels 353, 355, and 356, representing the "Divide" key 86 (FIG. 15). The Sequence Counter then switches the relay 491 (FIG. 49C) to enter the result of the subtraction operation into the "A" register and the switching of relay 569 (FIG. 45B) for transmitting the positive pressure signal over channel 568 (FIGS. 45B, 47B, and 47C) for up-counting by "one" the M/D counter (FIG. 47B) under the control of the relays 570a to 570c inclusive (FIG. 47C), which are turned on by the positive control signal over channel 613.

This operation continues until an overdraft signal over channel 464 (FIG. 49A) turns on the relays 571 (FIG. 47C), whereby the D.H. signal in channel 572 becomes positive. This signal is transmitted to the Sequence Counter (FIGS. 46A and 46B), which turns on the relays 581 and 582 (FIG. 42B), thereby transmitting a positive pressure signal over channel 291. This control signal (K_R) in channel 291 shifts the digits in each stage of the "M" register (FIG. 50) to the left. At this time, the digit stored in the relays 564 to 567 inclusive (FIG. 47B), which was transmitted over the output channels 618 to 621 inclusive (FIG. 47C) through the relays 606a to 606d inclusive, 607 to 610 inclusive, over the output channels 611 to 614 inclusive to the first stage of the "M" register, is entered into the first stage upon the switching of the relay 521 (FIG. 46C). The positive control signal in channel 572 is transmitted over the out-

put channel 622 of the relay 623 (FIG. 47C), which is turned on by the positive signal in channel 613. The positive control signal in channel 622 is transmitted through relay 629 to turn on relay 624, thereby transmitting a positive pressure signal from the input channel 280 over the output channel 625 to turn on the relays 615a to 615d inclusive. This operation results in the M/D counter's being reset to zero, as disclosed previously.

The control signal (K.B.O.F.) in channel 286a (FIG. 40B) is then checked. If this signal is negative, indicating that the "K" register has not been shifted back to its home position, the subtraction operation is repeated. This continues until the divisor in the "K" register has been shifted back to home position, at which time the control signal (K.B.O.F.) in channel 286a becomes positive.

The Sequence Counter then goes to T₄, at which time the quotient in the "M" register is printed in the manner described with relation to a multiplication operation. After this, the sequence counter then shifts through two clock operations to allow for the setting of the symbol row plates in the printing mechanism. At T₆, the Sequence Counter prints out the remainder of the division operation that is stored in the "A" register. At T₇, the various control signals are turned off, and the shift counter (FIGS. 40A and 40B) is reloaded from the buffer circuit in the manner described previously. The calculator is then at home position.

The three other control operations of the calculator are the Sub-Total, Total and Non-Add operations. Depression of the "Sub-Total" key 91 (FIG. 15) results in the digit "6" being transmitted over channels 353 to 356 inclusive (FIG. 42A). These control signals will print out the "A" register by producing a positive pressure signal in channel 410. If the "M" key 82 (FIG. 15) is also depressed at this time, a positive pressure signal is transmitted over channel 626 (FIG. 36) to the memory flip-flop (FIG. 42A), turning the flip-flop on, which conducts a positive pressure signal over channel 627. This signal switches the relays 521 and 516 (FIG. 46C), resulting in the amount stored in the "A" register being transferred to the "M" register, whereby the information is stored for use in a succeeding operation. Depression of the "Total" key 90 (FIG. 15) produces the binary digit "two" in the control channels 325 to 328 inclusive (FIG. 42A). These signals will be transmitted over channels 353 to 356 inclusive to turn on the relay 400b (FIG. 43), which turns on the relay 505, thereby providing a positive pressure signal over channel 410, which connects the "A" register to the printing mechanism. The control signals in channel 325 to 328 inclusive also operate the printer switch 404 (FIG. 43) upon the generation of the next clock signal over channel 285, whereby the "A" register is printed.

After the printing operation has occurred during the first clock cycle, the control signal on channel 281 (FIGS. 40C and 46C) becomes negative when the first clock cycle in channel 285 goes off. This control signal turns off the relay 486a (FIG. 46C), which transmits the positive pressure signal generated in the relay 518a. This signal turns on the relay 579, which resets the "A" register in the manner described previously. If the "M" key 82 (FIG. 15) is also depressed with the "Total" key, the operation is the same as that described above with relation to the "Sub-Total" key, wherein the "A" register is printed during the first clock cycle, and the relays 521, 579, are switched, which results in the setting of the "M" register equal to the "A" register and the resetting of the "A" register.

Depression of the "Non-Add" key 94 (FIG. 15) produces the digit "five" in channels 353 to 356 inclusive (FIG. 43), which results in the switching of the printer switch 404 upon the generation of the clock signal on channel 285 in the manner described previously. This results in the printing of the "K" register. If the "M" key 82 is also depressed at this time, a positive pressure

signal is generated over channel 627 (FIGS. 42A and 43), which turns on the relays 507, whereby a positive pressure signal is transmitted over channel 411 to the selector unit, so that the output channels of the "M" register will be connected to the printer to print the "M" register.

The four non-motorized keys mounted on the keyboard are the "%" key 81 (FIG. 115), whose function was described previously with regard to a multiplication operation; the "Mode" key 84, which normally disables the printing of either the "K" register or the "M" register; the "M" key 82, which controls the "M" register; and the "Clear" key 83, for resetting the calculator. The "Mode" key 84 may be used in conjunction with the "Add" key, the "Subtract" key, the "Multiply" key, the "Negative Multiply" key, and the "Enter Dividend" key. Each time the "Mode" key is depressed, a positive signal is transmitted over channel 403 (FIGS. 36 and 42A) to the memory flip-flop, which produces a positive pressure signal over the output channel 586. This signal turns on the relay 402 (FIG. 43), which disables the switching of the printer switch 404 except when the "Multiply" key has been depressed. As disclosed previously, this use of the "Mode" key with the "Multiply" key results in the printing of the "A" register.

The "Mode" key is also used in conjunction with the "M" key in an adding or subtracting operation. Under these conditions, the "Mode" key functions to disable the printing of the "M" register, which would normally occur if the "M" key had been depressed. The function of the "M" key 82 at this time is to normally generate a positive pressure signal over the control channel 411 (FIG. 43), which controls the selector unit, so that the output of the "M" register is connected to the printer. The "M" register is also connected to the adder at this time. Either of the "Add" or "Subtract" control keys will switch the relay 271 (FIG. 46C) to add the "M" register to the "A" register, while the "Mode" key will disable the printing of the "M" register.

Depression of the "Clear" key 83 (FIG. 15) results in the generation of a positive signal over channel 309 (FIG. 36) and channel 628 (FIG. 42A). This signal is transmitted to reset the Shift Counter (FIGS. 40A and 40B), the Symbol Row Printer logic circuit (FIGS. 45A and 45B), and the control circuits in FIGS. 46A, 46B, and 46C.

Referring now to FIGS. 55 and 56, there are shown two views of another type of relay construction which may be used in place of the flip-flop arrangement of each bit section of each stage of the storage registers. One major disadvantage of the type of fluid-actuated relay disclosed in FIG. 3 is that, in case of a power failure in which the fluid pressures are destroyed, the orientation of the pistons will be altered. In the case of the storage registers, information stored therein will be lost. In order to avoid this problem, a piston 630, similar in construction to the piston 62 (FIG. 3), is provided with a pair of apertures 631 and 632, each of which alternately coacts with a stop pin 633 (FIG. 56) when the piston 630 is in either a positive position or a negative position. The stop pin 633 is slidably mounted to one end of a crank arm 634, the arm being rotatably mounted on a shaft 635. The shaft 635 is reciprocally rotated by a motor (not shown) at a speed which corresponds to the time sequence of the clock signals generated by the clock circuit (FIG. 39). As shown in FIG. 56, a pair of stop pins are mounted on either end of the arm 634. A second piston 636 is provided to illustrate a flip-flop circuit of the type that may be substituted for the flip-flop circuit previously disclosed in relation to the storage registers of FIGS. 50, 51, and 52. As may be seen from FIG. 55, the output channel 66 of relay 636 is connected to the control port of relay 630. This relay 636 acts as the input flip-flop, while relay 630 is the memory flip-flop. In operation, when the stop pins 70 are in the position shown in FIG. 56, the input relay 636

is free to be reset, while the memory relay 630 is set by engagement of the stop pin 637 with either one of the apertures 631 or 632, depending on its position. Upon cycling of the shaft 635, the stop pin will engage the relay 636, while the pin 637 is removed from engagement with the relay 630, thus allowing the relay to be reset under the control of the pressure signal on channel 66 transmitted from relay 636. It will thus be seen that, when a power failure occurs, either one of the relays 630 or 636 will be in locked position, thus retaining its position until power is restored.

While there have been shown and described and pointed out the fundamental novel features of the invention as applied to the preferred embodiment, it will be understood that various omissions, substitutions, and changes in the form and details of the device illustrated and its operation may be made by those skilled in the art without departing from the spirit of the invention. It is the intention, therefore, to be limited only as indicated by the scope of the following claims.

What is claimed is:

1. In a printing hydraulic calculating apparatus capable of performing addition, subtraction, multiplication, and division operations, the combination including

(a) a ten-key keyboard having a plurality of amount and control keys each generating, when actuated, a plurality of fluid pressure signals representing a predetermined binary digit, said control keys including an add key;

(b) a source of fluid pressure signals;

(c) keyboard, memory, and accumulating shift registers each having a plurality of digit stages composed of fluid pressure relays capable of being orientated to store fluid pressure signals representing binary digits;

(d) printing means adapted for printing the decimal equivalent of the binary digits stored in said shift registers;

(e) a binary adder having a plurality of digit stages whose signals are connected to said accumulating register and to either of said memory or keyboard registers and whose outputs are connected to the accumulating register;

(f) first logic circuit means controlled by operation of said add key for generating fluid pressure timing signals for operating said printing means and said shift registers;

(g) and second logic circuit means controlled by operation of said add key for coupling said accumulating shift register to said printing means and said memory shift register, and said keyboard shift register to said binary adder whereby binary information in the form of fluid pressure signals generated by operation of said amount keys and stored in said keyboard register is added to said accumulating register and printed by said printing means.

2. The apparatus of claim 1 which includes an indicator mechanism for each of said shift registers, each of said indicator mechanisms including means for converting binary digits, stored in said shift registers in the form of fluid pressure signals, to their equivalent decimal digits.

3. In a printing hydraulic calculating apparatus capable of performing adding, subtracting, multiplying, and dividing operations, the combination including

(a) a ten-key keyboard having a plurality of amount and control keys each generating, when actuated, a plurality of fluid pressure signals representing a predetermined binary coded decimal digit, said control keys including an add key;

(b) a source of fluid pressure signals;

(c) keyboard, memory, and accumulating shift registers each having a plurality of digit stages composed of fluid pressure relays capable of being orientated to

tated to store fluid pressure signals representing binary coded decimal digits;

(d) printing means adapted for printing the decimal equivalent of the binary coded decimal digits stored in said shift registers;

(e) a binary coded decimal adder having a plurality of digit stages, each stage comprising an input section connected to said accumulating shift register and capable of being coupled to either of said keyboard or memory shift registers, a binary adder and carry circuit means, and an output section connected to said accumulating shift register;

(f) first code correction circuit means in said input section for adding the digit six to the binary coded decimal digits transmitted from either of the keyboard or memory shift registers;

(g) second code correction circuit means in said output section for subtracting the digit six from the digit generated by the adder circuit means upon the failure of the carry circuit means to generate a carry-representing fluid pressure signal;

(h) first logic circuit means controlled by operation of said add key for generating fluid pressure timing signals for operating said printing means and said shift registers;

(i) and second logic circuit means controlled by operation of said add key for coupling said accumulating shift register to said printing means and said memory shift register, and said keyboard shift register to said binary coded decimal adder whereby binary coded decimal information in the form of fluid pressure signals generated by operation of said amount keys and stored in said keyboard register is added to said accumulating register and printed by said printing means.

4. The apparatus of claim 3 which includes an indicator mechanism for each of said shift registers, each of said indicator mechanisms including means for converting the binary coded decimal digits, stored in the respective shift registers in the form of fluid pressure signals, to their equivalent decimal digits, and means adapted to be controlled by said converting means for displaying the equivalent decimal digit.

5. In a printing hydraulic calculating apparatus capable of performing addition, subtraction, multiplication, and division operations, the combination including

(a) a ten-key keyboard having a plurality of amount and control keys each generating, when actuated, a plurality of fluid pressure signals representing a predetermined binary digit, said control keys including a subtract key;

(b) a source of fluid pressure signals;

(c) keyboard, memory, and accumulating shift registers each having a plurality of digit stages composed of fluid pressure relays capable of being orientated to store fluid pressure signals representing binary digits;

(d) printing means adapted for printing the decimal equivalent of the binary digits stored in said shift registers;

(e) a binary adder having a plurality of digit stages whose input sections are connected to the accumulating register and capable of being coupled to either of said keyboard or memory shift registers and whose output sections are connected to said accumulating shift registers;

(f) a first control circuit means located in each input section of each stage of said adder for generating, when operated, the nine's complement of the digit transferred from either of said keyboard or memory shift registers to the input section;

(g) a second control circuit means located in each output section of each digit stage of said adder for generating, when operated, the nine's complement of the digit being transferred to the accumulating register;

- (h) first logic circuit means controlled by operation of said subtract key for generating fluid pressure timing signals for operating said printing means and said shift registers;
- (i) second logic circuit means controlled by operation of said subtract key for coupling said accumulating shift register to said printing means and said memory shift register, and said keyboard shift register to said binary adder;
- (j) and third logic circuit means controlled by operation of said subtract key for operating said first and second control circuit means whereby a binary number in the form of fluid pressure signals stored in said keyboard register is subtracted from a binary number in the form of fluid pressure signals stored in said accumulating register.
6. In a printing hydraulic calculating apparatus capable of performing adding, subtraction, multiplying, and dividing operations, the combination including
- (a) a ten-key keyboard having a plurality of amount and control keys each generating, when actuated, a plurality of fluid pressure signals representing a predetermined binary coded decimal digit, said control keys including a subtract key;
- (b) a source of fluid pressure signals;
- (c) keyboard, memory, and accumulating shift registers each having a plurality of digit stages composed of fluid pressure relays capable of being orientated to store fluid pressure signals representing binary coded decimal digits;
- (d) printing means adapted for printing the decimal equivalent of the binary coded decimal digits stored in said shift registers;
- (e) a binary coded decimal adder having a plurality of digit stages, each stage comprising an input section connected to said accumulating shift register and capable of being coupled to either of said keyboard or memory shift registers, a binary adder and carry circuit means, and an output section connected to said accumulating shift register;
- (f) first code correction circuit means in said input section including means for adding the digit six to the binary coded decimal digits transmitted from either of the keyboard or memory shift registers, and means for generating, when operated, the nine's complement of the digits so altered;
- (g) second code correction means in said output section including means for subtracting the digit six from the digit generated by the adder circuit means upon failure of the carry circuit means to generate a carry-representing fluid pressure signal, and means for generating, when operated, the nine's complement of the digit being transferred to the accumulating register;
- (h) first logic circuit means controlled by operation of said add key for generating fluid pressure timing signals for operating said printing means and said shift registers;
- (i) second logic circuit means controlled by operation of said add key for coupling said accumulating shift register to said printing means and said memory shift register, and said keyboard shift register to said binary coded decimal adder whereby binary coded decimal information in the form of fluid pressure signals generated by operation of said amount keys and stored in said keyboard register is added to said accumulating register and printed by said printing means;
- (j) and third logic circuit means controlled by operation of said subtract key for operating said means for generating the nine's complement of the digit in the input and output sections of the adder whereby a binary coded decimal number in the form of fluid pressure signals stored in said keyboard register is subtracted from a binary coded decimal number in the form of

- fluid pressure signals stored in said accumulating register.
7. In a printing hydraulic calculating apparatus capable of performing addition, subtraction, multiplication, and division operations, the combination including
- (a) a ten-key keyboard including a plurality of amount keys each producing a plurality of fluid pressure signals when depressed, said fluid pressure signals representing a predetermined binary digit equal to the numerical value of the key depressed;
- (b) a source of fluid pressure signals;
- (c) a keyboard shift register having a predetermined number of storage stages, each stage capable of storing a binary digit generated by operation of an amount key;
- (d) channel means connected between said keyboard and said register for transmitting digit-representing fluid pressure signals from said keyboard to said register for storage therein;
- (e) a shift counter having a plurality of fluid pressure storage relays for storing a binary digit representative of the number of amount key operations;
- (f) first logic circuit means operated by said shift counter for generating a first fluid pressure control signal for disabling the operation of said keyboard;
- (g) means for generating a second fluid pressure control signal upon initiation of the first amount key operation of the keyboard;
- (h) means for generating a third fluid pressure control signal upon each amount key operation of the keyboard;
- (i) second logic circuit means coupled to said storage relays and normally operated by said third fluid pressure control signal for transmitting to said relays the next highest binary digit;
- (j) and means operated by said second and third fluid pressure control signals for storing in said storage relays a predetermined binary digit so that upon the subsequent operation of the keyboard the number of which is equal to the capacity of the shift register, each of the storage relays will be similarly orientated so as to operate said first logic circuit means, thereby disabling said keyboard.
8. In a printing hydraulic calculating apparatus capable of performing addition, subtraction, multiplication, and division operations, the combination including
- (a) a ten-key keyboard having a plurality of amount keys slidably mounted therein, each of said keys adapted to generate a positive fluid pressure signal when depressed;
- (b) a plurality of fluid pressure relays associated with each amount key and including a first two-position fluid pressure relay having first and second output ports, a control port, and first, second, and third input ports, and having a pressure-responsive means operative in a first of said two positions to connect said first and second input ports to said first and second output ports respectively, and in a second of said two positions upon the application of a positive pressure signal in said control port to connect said second and third input ports to said first and second output ports; and a second two-position fluid pressure relay having a control port for controlling said relay to one of either of said two positions for generating fluid pressure signals representing a predetermined binary digit;
- (c) a first fluid pressure conduit means connected between the second output port of said first pressure relay of each amount key to the second input port of the first pressure relay of the next highest amount key;
- (d) a source of positive fluid pressure signals connected to said first conduit for transmission to said first relay of each amount key;

75

- (e) a second fluid pressure conduit means connected between the first output port of each of said first fluid pressure relay and the control port of the associated second fluid pressure relay;
- (f) and third fluid pressure conduit means connected between each of said amount keys and the control port of the associated first fluid pressure relay whereby upon depression of one of said amount keys, the second input port of said first relay will be connected to the first output port of said relay, thereby actuating said second relay while disabling each succeeding higher amount key from actuating the second fluid pressure relay.
9. In a printing hydraulic calculating apparatus capable of performing addition, subtraction, multiplication, and division operations, the combination including
- (a) a ten-key keyboard having a plurality of amount keys slidably mounted therein, each of said keys being adapted to generate a control fluid pressure signal when depressed;
- (b) a plurality of fluid pressure relays controlled by each amount key and including a first relay having first and second output ports, a control port, and at least one input port, and having a pressure-responsive means operated in a first of said two positions to connect said input port to said first output port, and in a second of said two positions, upon the application of said control fluid pressure signal in said control port, to connect said input port to said second output port; and a second fluid pressure relay having a control port for operating said relay to generate fluid pressure signals representing a predetermined binary digit;
- (c) a first channel means connected between the first output port of said first pressure relay of each amount key to the input port of the first pressure relay of the next highest amount key;
- (d) a source of fluid pressure signals connected to said first channel for transmission to said first relay of each amount key;
- (e) a second fluid pressure channel means connected between the second output port of each of said first fluid pressure relay and the control port of its associated second fluid pressure relay;
- (f) and a third fluid pressure channel means connected between each of said amount keys and the control port of its associated first fluid pressure relay whereby, upon depression of one of said amount keys, the input port of said first relay will be connected to the second output port of said relay, thereby actuating said second relay while disabling each succeeding higher amount key from actuating their second fluid pressure relay.
10. In a printing hydraulic calculating apparatus capable of performing adding, subtracting, multiplying, and dividing operations, the combination including
- (a) a ten-key keyboard having control and amount keys, each of the keys being adapted for generating, when depressed, a plurality of primary fluid pressure signals representing a predetermined binary digit;
- (b) a source of fluid pressure signals;
- (c) a keyboard shift register having a plurality of digit stages for storing said primary fluid pressure signals representing the binary digits generated by said amount keys;
- (d) fluid pressure relay means operated by the primary fluid pressure signals generated by depression of one of said control keys for generating like secondary fluid pressure signals, thereby allowing said depressed control key to be released;
- (e) first logic circuit means operated by said secondary fluid pressure signals for generating a series of fluid pressure timing signals;
- (f) second logic circuit means operated by said sec-

- ondary fluid pressure signals for generating a series of control fluid pressure signals representing the control key depressed;
- (g) printing means including a binary-to-decimal code converting mechanism operated by said primary control fluid pressure signals, representing the control and amount keys depressed, for controlling said printing means to print, when operated, the decimal equivalent of the amount keys depressed and a symbol representing the control key depressed;
- (h) means interconnecting said keyboard shift register and said second logic circuit with said printing means for transmission of said fluid pressure signals thereto;
- (i) means for operating said printing means when actuated;
- (j) and third logic circuit means controlled by said secondary fluid pressure signals for transmitting one of said timing signals to said operating means for actuation thereof, whereby said printing means is operated.
11. The printing hydraulic calculating apparatus of claim 10 wherein said binary-to-decimal code-converting mechanism includes
- (a) a plurality of code-converting notched slides, each slide selectively movable to a first position for aligning a set of notches representative of a decimal number;
- (b) means for urging each of said slides to said first position;
- (c) first means for sensing said aligned notches for controlling the printing means to print the decimal number represented by the aligned notches;
- (d) and means for selectively controlling the movement of each of said slides, including
- a latching member for latching each of said slides out of said first position;
- a plurality of piston members each adjusted for movement to an actuated position by said primary fluid pressure signals;
- and second means for sensing the position of said piston members, said second sensing means being adapted for disabling said latch member upon sensing a piston member in an actuated position whereby the selected code-converting notched slides are moved to a first position to control the printing means to print the decimal number represented by the primary fluid pressure signals.
12. The printing hydraulic calculating apparatus of claim 11 wherein said second sensing means includes
- a movable carriage member slidably supporting said latching member;
- blocking means connected to said piston members, each blocking member being positioned adjacent one of said latching members and adapted to be moved to a non-blocking position upon actuation of its associated piston member;
- and means for moving said carriage member to allow each latching member to sense the position of its associated blocking member whereby a latching member is moved to an unlatching position by said carriage upon movement of its associated blocking means to an unblocking position.
13. In a printing hydraulic calculating apparatus capable of performing addition, subtraction, multiplication, and division operations, the combination including
- (a) a binary adder having a plurality of digit stages, each stage including an adder section and a digit carry generating logic circuit means;
- (b) a two-position first fluid pressure relay means associated with each digit section, said relay having an input port, a control port, an output port, and a fluid pressure responsive means operative by a fluid pressure signal in said control port for movement to the

- first of said two positions to connect said input port to said output port;
- (c) means connecting the output port of said first pressure relay of each digit stage of the adder to the input port of the first pressure relay and the adder section of the next digit stage;
- (d) second fluid pressure relay means located in each digit carry generating circuit for generating said fluid pressure signal representing a digit carry signal;
- (e) and means for transmitting said fluid pressure signal to the control port of the associated first fluid pressure relay means whereby a digit carry signal in said connecting means is transmitted simultaneously to a number of digit stages.

14. In a printing hydraulic calculating apparatus capable of performing addition, subtraction, multiplication, and division operations, the combination including

- (a) a binary adder having a plurality of digit stages, each stage including an adder section and logic circuit means for generating a carry-representing fluid pressure signal;
- (b) fluid pressure relay means associated with each stage of the adder, said relay means having an input port, an output port, and selecting means for interconnecting, when operated, said input port and said output port;
- (c) first means interconnecting the output port of the fluid pressure relay means of each stage of the adder to the input port of the fluid pressure relay means and the adder section of the next stage of the adder;
- (d) and second means interconnecting the logic circuit means and the selecting means of the associated fluid pressure relay means whereby generation of a carry-representing fluid pressure signal by said logic circuit means will operate the selecting means to allow a carry-representing fluid pressure signal in said first interconnecting means to be transmitted simultaneously to a number of digit stages of the adder.

15. In a printing hydraulic calculating apparatus capable of performing adding, subtracting, multiplying, and dividing operations and having a source of fluid pressure signals, a bi-stable fluid-operated device comprising

- (a) a first fluid-pressure-operated relay having at least one input port, one output port, and one control port, a fluid-pressure-actuated piston member movable to a first position for connecting said input port to said output port;
- (b) a second fluid-pressure-operated relay having at least one input port, one output port, and one control port, a fluid-pressure-actuated piston member movable to a first position for connecting said input port of said second relay to said output port of said second relay;
- (c) a first fluid-pressure-conducting means connecting the output port of said first relay to said control port of said second relay;
- (d) a second fluid-pressure-conducting means connecting the output port of said second relay to said input port of said first relay;

- (e) a third fluid-pressure-operated relay;
- (f) a third fluid-pressure-conducting means connecting the output port of said second relay to said third fluid-pressure-operated relay for transmission of fluid pressure signals thereto;
- (g) and means alternately engaging each of said fluid-pressure-actuated piston members of said first and second relays when in said first position, thereby locking said piston members in said positions upon failure of the source of the fluid pressure signals.

16. In a printing calculating apparatus capable of performing adding, subtracting, multiplying, and dividing operations, a bi-stable fluid-operated device comprising

- (a) a source of fluid pressure signals;
- (b) a first fluid-pressure-operated relay having at least one input port, one output port, and one control port, a fluid-pressure-actuated piston having an aperture located therein and adapted to be moved to a first position for connecting said input port to said output port;
- (c) a second fluid-pressure-operated relay having at least one input port, one output port, and one control port, a fluid-pressure-actuated piston having an aperture located therein and adapted to be moved to a first position for connecting said input port of said second relay to said output port of said second relay;
- (d) a first fluid-pressure-conducting means connecting the output port of said first relay to said control port of said second relay;
- (e) a second fluid-pressure-conducting means connecting the output port of said second relay to said input port of said first relay;
- (f) a third fluid-pressure-operated relay;
- (g) a third fluid-pressure-conducting means connecting the output port of said second relay for transmission of fluid pressure signals thereto;
- (h) and means alternately engaging each of said pistons when in said first position, including a lever member mounted adjacent said first and second relays, a pin rotatably mounted on each end of said lever and adapted to be moved into the aperture of one of said pistons for locking said piston in said position and means for oscillating said lever member whereby one of said pistons is locked in position upon a failure of said source of fluid pressure signals.
